SLUG CASTING MACHINE

James C. Plastaras, Laurelton, N. Y., assignor to
 Mergenthaler Linotype Company, a corporation
 of New York

Application March 13, 1941, Serial No. 383,133

131 Claims. (Cl. 199—11)

This invention relates to typographical slug casting machines of the general organization represented in U. S. Letters Patent to O. Mergenthaler, No. 436,532, wherein a composed line of matrices and spacebands is transferred to a first elevator, justified between a pair of vise jaws and then locked up against the face of a slotted mold which is thereafter filled with molten metal to cast a slug or linotype against the justified line. More particularly, it relates to the vise jaw and justifying mechanisms of such machines.

The vise jaw and justifying mechanisms herein shown and described form part of a machine which is substantially new in its entirety. Many phases of the new machine are dealt with in the Plastaras copending applications Serial Nos. 269,833, 311,091, 355,434, and 377,364, filed respectively on April 25, 1939, December 27, 1939, September 5, 1940, and February 4, 1941. Other phases will be dealt with in applications yet to be filed.

Among other things, the invention has achieved economy in manufacture by operating the jaws and the spaceband driver from individual power units, compactly mounted in the vise frame, under the control of a small light cam shaft unit which acts automatically to time the various operations of the parts. The arrangement has dispensed with the heavy power transmitting cam shaft as well as the long ponderous levers and connections which have heretofore been necessary.

Perhaps the best way to understand the improved vise jaw mechanism is to consider it as a line quadding and centering attachment. Actually, when the machine is at rest, both jaws are urged outwardly by power devices individual to the respective jaws. However, after the line has been positioned between the jaws and the machine cycle inaugurated, the power devices reverse the forces acting upon the jaws, urging them inwardly to their casting positions. After casting, the forces acting upon the jaws are again reversed, to reestablish the original conditions, so that the composed line may be withdrawn from between the jaws for distribution.

The various conditions of machine operation are determined by permitting free movement of the jaws by the forces which act upon them or by limiting their inward movement through the medium of adjustable stops which may be selectively interposed in the paths of the jaws. Thus, when it is desired to cast a line of full length (regardless of its actual length), a stop adjusted to full line position is interposed in the path of

each jaw to prevent its movement inwardly beyond the adjacent end of the mold slot. Different settings of the stops will produce lines of correspondingly different measures. Moreover, by setting the stops inwardly from their full line positions, the inward quadding movement of the jaws will be arrested to give a fixed indentation at either or at both ends of the line, as may be desired.

For free or random quadding with either jaw, the stop associated therewith is disabled, permitting the casting position of that jaw to be determined by direct contact with the line when backed up by the other fixed jaw, whose casting position is determined by its stop which remains active. For a centering operation, both stops are disabled and the jaws coupled together for equi-distant movement so that their casting positions will be determined by direct contact with the line when it has assumed its centered position.

In the preferred arrangement, the jaws are pneumatically operated by separate and distinct cylinder and piston devices controlled by automatically operated valves which alternately charge and vent the cylinders to urge the jaws inwardly and outwardly at the proper stages in the machine cycle. Hydraulic mechanisms, one for each jaw, exert clamping pressure to hold the jaws in their casting positions. When both jaw stops are active, as will be the case when a line of full measure is cast, or when the stops are set for fixed indentation at either or at both ends of the line, the hydraulic mechanisms will hold the jaws firmly against their stops as the spacebands are driven up to justify the line as well as during the slug casting operation. When both stops are inactive, as in centering, the hydraulic mechanisms will act to produce a line squeeze, since, under those conditions, the line itself is all that determines the casting positions of the jaws.

During random quadding with either jaw, the hydraulic mechanism associated with the fixed jaw will hold it firmly against its stop, whereas that associated with the quadding jaw, whose stop is inactive, will exert a squeezing pressure upon the line, since under this condition, too, the line itself determines the casting position of the quadding jaw. In such free quadding operations with one jaw alone, a differential is set up in the pressures applied by the two hydraulic mechanisms in favor of the jaw whose stop is active, in order to preclude the possibility of that jaw being backed away from its stop by the pres-

sure exerted through the line by the opposed quadding jaw.

The hydraulic clamping pressure is automatically applied after the jaws have been positioned by their pneumatic operating devices and just prior to first justification. After the first justifying operation, the clamping pressure is relieved to permit matrix alignment to take place. Thereafter, the clamping pressure is restored preparatory to second justification, the pressure remaining effective until after the casting of the slug. While the application and relief of the hydraulic clamping pressure is timed from the cam shaft in the vise frame, the force necessary to relieve the clamping pressure is supplied by an independent pneumatic device, since the structural characteristics of the cam shaft render it inadvisable to use the same as a force transmitting element. The operation of such pneumatic pressure relieving device is nevertheless timed from said cam shaft.

The improved justification mechanism comprises an individual power unit in the form of a pneumatically operated cylinder and piston device automatically controlled from the cam shaft. Since the first justifying operation merely serves to expand the line preliminarily to fill up the space between the jaws and does not contemplate a tightness in the line such as must result from second justification, the pneumatic pressure exerted during first justification is substantially less than that exerted during second justification. To this end, a pressure regulating valve is inserted in the line through which air is supplied to the justification cylinder for carrying out the justifying operations, this pressure regulating valve serving to limit the justifying force exerted upon the spacebands during first justification to a predetermined amount and then acting automatically to permit a larger force of predetermined amount to be exerted on the spacebands during second justification. Between the two stages of justification, the pneumatic pressure exerted on the spaceband driver is relieved to facilitate the matrix alignment operation already referred to.

A manually adjustable control element within easy reach of the operator enables the machine readily to be conditioned for regular machine operation, quadding left, centering, and quadding right as desired, and upon the setting of the device for any selected operation, the machine without more is automatically conditioned for the performance of that operation.

Other features of the new machine will be apparent from the following detailed description.

Fig. 26 is a diagram of the pneumatic system.

Vise jaws and their mounting

As set forth in the Plastaras application Serial No. 377,364, the new machine, of which the instant mechanisms form part, utilizes a line delivery carriage A equipped with a pair of line engaging fingers A¹ and A² acting, upon the inauguration of the line transfer operation, to descend into engagement with the opposite ends of a composed line of matrices and spacebands, whereupon the line delivery carriage moves to the left, transferring the line directly from the assembler to the first elevator A³ which, in its normal position, stands at the assembling level (Fig. 2). Upon the delivery of the line to the first elevator, the line engaging fingers A¹ and A² ascend clear

of the line, permitting the line delivery carriage to be restored to its normal position ready for the transfer of the next line.

The machine is equipped with a vise frame B supporting right and left-hand jaws C and C¹ between which the line is clamped endwise during the casting operation. The left-hand jaw C¹, at all times, is located at the casting level, whereas the right-hand jaw C normally stands below the delivery path of the line so that the matrices and spacebands can pass over it without interference during the line delivery operation (Fig. 1). When the line has cleared the right-hand jaw and has been delivered to the first elevator, the right-hand jaw ascends to an operative line clamping level, i. e., to the level of the left-hand jaw, so that the composed line will be located between them (Fig. 2).

The right-hand jaw comprises a body portion C², tongued and grooved for longitudinal sliding movement in a jaw support C³, and a rearwardly offset portion c whose left or active face is adapted to engage the terminal end of the line (Figs. 2 and 4). The jaw support C³ is arranged for vertical sliding movement to permit the ascent and descent of the right-hand jaw, and for this purpose it is channelled vertically at the front to provide clearance for a fixed guiding member B¹ forming part of the vise frame, the guiding member being formed in its lateral edges with grooves B² to receive a pair of vertical guiding tongues C⁵ screwed to the jaw support adjacent its front face (Figs. 2 and 9). The ascent and descent of the jaw is effected by a vertically arranged pneumatically operated double-acting cylinder and piston mechanism whose cylinder C⁶ is fixed on the vise frame and whose piston rod C⁷ extends through the head of the cylinder and is connected at its upper end to a lug C⁸ projecting rearwardly from the jaw support (Figs. 1, 2, 4 and 9).

Both ends of the cylinder C⁶ are connected by pipe lines C⁹ and C¹⁰ to a valve C¹¹ adjustable by means of a swivel bar C¹² to two different positions. In one position of the valve, the cylinder is charged with air pressure at one end and vented to the atmosphere at the other; whereas, in the other position of the valve, the pressure conditions in the cylinder are reversed (Figs. 1, 2 and 26). Normally, the cylinder is charged at the top, thus locating the jaw C in its lowermost position, where it is held by a latch member C¹³ whose function and operation have been described in the aforementioned copending application Serial No. 377,364. However, as the line delivery carriage A completes its line delivery movement, it actuates a slide A⁴ which, through the medium of a pair of levers C¹⁴ and C¹⁵ and an interconnecting link C¹⁶, moves a swivel lever C¹⁷ to the position shown in Fig. 2, thereby adjusting the valve C¹¹ to charge the cylinder C⁶ at its lower end and vent it at the top, with the result that the right-hand jaw C is raised to its upper or active position. The swivel member C¹⁷ is pivotally mounted on a fixed fore-and-aft rod B³ and is formed with three arms C¹⁸, C¹⁹ and C²⁰, the arm C¹⁸ extending upwardly and presenting a bifurcated portion which engages a pin C²¹ at the lower end of its actuating lever C¹⁵, the arm C¹⁹ extending to the right and presenting a bifurcated portion engaging one end of the valve adjusting swivel member C¹², and the arm C²⁰ extending downwardly and presenting at its lower end a cam follower C²² which is arranged to track along an edge cam D¹ mounted upon a fore-and-aft cam shaft D journaled at its opposite ends in the vise

frame B. The cam makes one complete rotation in each machine cycle of operation and at the proper stage in the cycle, i. e., after the actual casting of the slug has taken place, a high portion D² of the cam D¹ engages the follower and turns the swivel member C¹² back to its original position, with the result that the valve C¹¹ is adjusted to charge the cylinder at its upper end and vent it at its lower end, thus moving the right-hand jaw C downwardly to its normal inoperative position. During the final stages of its upward movement, the right-hand jaw inauguates the casting cycle, i. e., it initiates the rotation of the cam shaft D, which, after one complete rotation, is automatically brought to rest.

The left-hand jaw C¹ is substantially U-shaped in cross-section, being formed with a rear portion or leg C²³ whose right end is adapted to engage the left or leading end of the composed line (Figs. 2 and 3). The jaw is also formed with a front leg portion C²⁴ which is guided for end-wise movement between a depending apron B⁴, forming part of a cap B⁵ at the top of the vise frame, and a fixed portion B⁶ of the vise frame proper, the leg C²⁴ being formed at the top with a forwardly projecting portion C²⁵ presenting a shoulder which engages the top surface of the vise frame portion B⁶ just alluded to. In this way, the jaw is supported at the proper level. As in the case of the right-hand jaw C, the left-hand jaw C¹ is formed in its line engaging face with a vertical groove C²⁶ so that, when necessary, it will accommodate the left-hand finger A² of the line delivery carriage A upon the initial movement of the line into the first elevator, assuming of course the line is long enough substantially to fill out the space between the jaws (Fig. 6).

The jaw stops and their adjusting mechanism

The line clamping jaws C and C¹ are movable, each toward the other, separately for quadding the line at either end or simultaneously for centering the line. Actually, during each machine cycle, forces act to urge both jaws toward each other to line clamping position before casting and away from each other after casting to restore them to their normal positions. During a centering operation, the jaws move toward each other until they are arrested by banking against the opposite ends of the composed line, provision being made, as will be described later on, for equalizing the jaw movement under such conditions. Free or random quadding with either jaw is effected merely by selectively interposing a stop in the path of the other jaw to locate it in its full line position, while allowing the casting or quadding position of the other jaw to be determined by direct contact with the line. Since each jaw has associated with it a stop which is adjustable to any desired position, the two stops may be used to determine the casting positions of both jaws, and since the line can be justified out to fill up the space between the jaws, the arrangement permits a fixed degree of quadding, termed a fixed indentation, at either end or at both ends of the line. The stops are also used when a line of full measure is cast, being located under such conditions in non-quadding or full line positions; in other words, since the jaws are powered to move inwardly and outwardly during each machine cycle, regular or full line casting may be considered as a special condition of fixed indentation, namely, a condition giving a zero indentation at both ends of the line.

The stops under discussion are designated E

and E^1 (Figs. 2, 3, 4 and 6). When in use, the stop E is interposed in the path of a lug C^{27} extending forwardly from the right-hand jaw C , whereas the stop E^1 is interposed in the path of a lug C^{28} extending forwardly from the left-hand jaw C^1 . The stops E and E^1 project rearwardly from a corresponding pair of racks E^2 and E^3 , which are tongued and grooved in a fixed portion of the vise frame B and are arranged for independent horizontal movement in a direction laterally of the machine so that the stops can be individually adjusted for any machine condition desired.

The racks E^2 and E^3 are held in their different positions of adjustment by a corresponding pair of locking bolts E^4 and E^5 extending through sleeves or bushings E^6 and E^7 mounted in a fore-and-aft direction in fixed portions of the vise frame (Figs. 1, 2, 3, 4, 6, 7 and 18). For this purpose, the racks E^2 and E^3 , throughout their entire front faces, and the locking bolts E^4 and E^5 in their rear end faces, are formed with vertical, regularly pitched teeth E^8 and E^9 which interengage in any of the adjusted positions of the racks. The locking bolts for the two jaw stops are the same and are illustrated best in Figs. 7 and 18. Throughout the rear half of their length, i. e., where they are encircled by the sleeves E^6 and E^7 , the bolts E^4 and E^5 are cylindrical in shape; forward, however, they are cut away each to present two diametrically opposed rods E^{10} located one above the other in a vertical plane and integrally connected at their outer ends by an annular ring E^{11} . The diametrically opposed rods E^{10} extend forwardly through a vertical slot E^{12} formed in a keeper plate E^{13} , E^{14} , there being one keeper plate for each bolt. The keeper plates are connected to the vise frame at the front each by a pair of screw and slot connections E^{15} . Each bolt is hollowed out to form a recess E^{16} which houses a compression spring E^{17} reacting between the rear end of the recess and the rear face of its respective keeper plate E^{13} , E^{14} . Thus, the bolts are urged rearwardly to maintain a locking engagement with their associated racks E^2 , E^3 .

The stops E and E^1 are adjusted manually from the front of the machine by a pair of knobs E^{18} and E^{19} , secured to the outer ends of a pair of shafts E^{20} and E^{21} extending in a fore-and-aft direction and mounted in cylindrical recesses in the vise frame. For the greater portion of their length, the shafts E^{20} and E^{21} are formed with pinion teeth E^{22} which, near the rear ends of the shafts, engage teeth E^{23} formed in the upper edges of the racks E^2 and E^3 associated with the respective jaw stops (Figs. 1, 2, 4, 6 and 18). Before either of the stops can be adjusted, its locking bolt must first be withdrawn out of locking engagement with its stop racks. For this purpose, there is provided a pair of levers E^{24} and E^{25} associated, respectively, with the right and left-hand locking bolts E^4 and E^5 . The levers are pivotally mounted at their lower end and provided each, about midway of its length, with a pin E^{26} engaging the rear face of the ring portion E^{11} of its associated locking bolt E^4 , E^5 and, near its upper end, with another pin E^{27} engaging in an annular groove E^{28} formed in the hub part of the associated adjusting knob E^{18} , E^{19} . To adjust either of the stops E , E^1 , then, the operator pulls forward on the appropriate knob E^{18} , E^{19} , thereby rocking the associated lever E^{24} , E^{25} to withdraw its locking bolt E^4 , E^5 out of engagement with the corresponding rack

E^2 , E^3 , thus freeing the rack for movement and permitting the operator to rotate the knob which in turn, through its pinion, adjusts the rack and consequently the stop in one direction or another, depending upon the direction in which the knob is rotated. When the proper adjustment has been made, the knob is released, whereupon the locking bolt is restored into engagement with its associated rack under the action of its compression spring E^{17} , the spring acting also to restore the adjusting knob and pinion rearwardly to their normal positions through the lever connection previously mentioned. When the locking bolts E^4 , E^5 are retracted out of engagement with the racks, they are held against inadvertent rotary movement such as would prevent reengagement, by the cooperation of their forwardly extending rods E^{10} with the vertical slots E^{12} in their respective keeper plates E^{13} , E^{14} .

The adjusted positions of the jaw stops E and E^1 are indicated by a pair of fingers E^{29} and E^{30} provided, one for each jaw, and which cooperate with a horizontally arranged scale E^{31} fastened at the front of the vise cap and graduated in ems (Fig. 1). The finger E^{29} , associated with the right-hand jaw C , is mounted at the left end of a rack E^{32} , whereas the finger E^{30} , associated with the left-hand jaw C^1 , is mounted at the right end of a similar rack E^{33} , the racks being tongued and grooved each to an underlying fixed member supported by the vise frame near the front (Figs. 4, 5 and 18). The racks E^{32} and E^{33} are arranged for longitudinal movement laterally of the machine in synchronism with the movement of the stop racks E^2 and E^3 , and, for this purpose, they are formed in their upper edges with teeth E^{34} meshing with the pinion teeth E^{22} by which the associated stop racks are adjusted. In other words, when the operator rotates the knobs E^{18} , E^{19} to adjust the stops E , E^1 , the fingers E^{29} , E^{30} associated with the stops will be correspondingly adjusted, so that by glancing at the position of the fingers with respect to the scale E^{31} the operator will be apprised at once of the position of the stops. In Fig. 1, the finger E^{29} associated with the right-hand jaw is set at "0" on the em scale (the scale being graduated from right to left), thus indicating that the stop E associated with the right-hand jaw is in its extreme rightmost position. The finger E^{30} associated with the left-hand jaw, on the other hand, is set at "18" on the em scale, indicating that the stop E^1 associated with the left-hand jaw is adjusted to produce an indentation at the left end of the slug of 12 ems, the line under such an adjustment of the stops to be 18 ems in length. The finger would also have the same setting if the length of the mold slot were 18 ems, since the stop E^1 is also used to locate the left-hand jaw according to the length of the slot in the mold in use. If a 30 em line were to be cast, the finger associated with the right-hand jaw would have the same zero setting indicated in Fig. 1, whereas the finger associated with the left-hand jaw would be set at "30" on the em scale. For an indentation at the right end of the line, the finger E^{29} associated with the right-hand jaw would be adjusted in the manner stated according to the extent of the indentation desired.

Although the scale E^{31} is graduated in ems as shown in Fig. 1, the pitch of the teeth on the stop racks E^2 , E^3 and of the cooperating teeth on the locking bolts E^4 , E^5 is a half em. Consequently, it follows that lines in multiples of

a half em indented at either end as desired may be cast with the adjusting devices that have been described.

The machine is also equipped with mechanism for varying the position of the stops E and E¹ by increments of less than a half em; indeed, variations in line length down to increments of one point can be obtained, if desired. To this end, the locking bolts E⁴ and E⁵ are eccentrically mounted in their encircling sleeves E⁶ and E⁷. The sleeves are formed near their front ends with flanges E³⁴, E³⁵ presenting shoulders which engage portions of the vise frame so as to hold the sleeves against rearward movement. Forward movement of the sleeves is prevented by the keeper plates E¹³, E¹⁴ which present the reaction surfaces for the springs in the locking bolts. As shown in Figs. 18 and 20, the sleeves are formed with what in effect are small crank arms E³⁶, E³⁷ consisting each of a fore-and-aft horizontal portion connected at one point with its associated flange, and a downwardly extending vertical portion terminating in another horizontal portion which extends forwardly through a vise frame front plate B⁷. The crank arms are connected to the sleeves at the point of greatest radius from the center of the associated locking bolt. Assuming now that the crank arm E³⁷ associated with the left-hand jaw is located in its rightmost position, as indicated by the solid lines in Fig. 17, the locking bolt E⁵ for that setting will be in its leftmost position. Now if the crank arm is turned to the dotted line position indicated in Fig. 17, the locking bolt E⁵ will be moved toward the right because of the eccentric nature of its encircling sleeve E⁷. In other words, while the coarser em adjustments of the stops are effected by moving the racks on which they are mounted while holding the locking bolts stationary, the finer point adjustments are made by moving the locking bolts themselves while maintaining them in locking engagement with the stop racks.

The full range of locking bolt adjustment is equivalent to six points, or a half em, and adjacent the crank arms E³⁶, E³⁷, there are mounted arcuate scales E³⁸ and E³⁹ graduated in points and screwed to the front plate B⁷ where the crank arms extend therethrough. Thus, by way of example, if the stop E¹, associated with the left-hand jaw, has been adjusted to the position where the pointer E³⁰ is opposite "18" on the em scale E³¹ (see the solid line position in Fig. 17) and the crank arm E³⁷ is opposite "0" on the point scale E²⁹, the adjustment of the crank arm to the dotted line position opposite "6" on the point scale will have the effect of moving the stop E¹ one half em to the right. This movement of the stop will be indicated by the finger E³⁰ cooperating with the em scale since, as stated previously, the stop racks E² and E³ and the finger racks E³² and E³³ are arranged for synchronous movement. Of course, the adjustment of the crank arm to any of the other point scale indications will result in a correspondingly smaller adjustment in the position of the stops.

In order to maintain the different adjustments, the sleeve associated with each locking bolt E⁴, E⁵ is formed in the peripheral edge of its flange, in a region diametrically opposite its associated crank arm, with a series of notches E⁴⁰ adapted to cooperate with a spring pawl E⁵¹ fixed to the vise frame above the sleeve flange, the pawl being formed at its end with a tooth adapted to enter one or another of the notches, depending

upon the setting of the sleeve (Fig. 20). The lightness of the spring pawl enables it to be cammed out of the notches E⁴⁰ as the sleeve is manually adjusted, but is strong enough, on the other hand, to prevent inadvertent rotation of the sleeve that might otherwise result from the lateral thrust of the jaw.

It should be stated here that the screw and slot connections E¹⁵, which hold the keeper plates E¹³, E¹⁴ against the reaction of the locking bolt springs E¹⁷, permit said plates to accommodate themselves to the lateral movement of the locking bolts as the latter are adjusted, while the vertical movements thereof are accommodated by the vertical slots E¹² in the keeper plates which are long enough for the purpose.

Provision is also made for limiting the outward adjustment of the finger pieces E²⁹ and E³⁰ beyond the zero and 30 em indications on the em scale, respectively (Figs. 1, 6 and 18). It will be observed that the finger pieces are formed at their lower ends with integral horizontal portions E⁴¹ and E⁴² by which they are connected to their respective racks E³² and E³³. These horizontal portions present shoulders which bank respectively against depending legs of a pair of angle plates E⁴³ and E⁴⁴ in their extreme outer positions of adjustment. The angle plates are secured to the vise frame at the front, their horizontal legs overlapping for a short distance the cylindrical recesses in which the elongated pinions E²⁰ and E²¹ are mounted, thus serving the additional function of limiting the extent to which the pinions can be pulled outwardly during the adjustment of the stops.

The pneumatic jaw operating mechanism

The jaws C and C¹ are pneumatically operated by cylinder and piston devices normally charged to urge the jaws apart but which have their charges reversed to urge the jaws inwardly to casting position at the proper stage in the machine cycle, namely, when the line is in the first elevator and the right-hand jaw has ascended to its upper position. Then, after the actual casting operation has taken place, the charges in the pneumatic devices are again reversed, causing the jaws to retreat from the ends of the line and enabling the line to ascend to the upper transfer level for distribution.

Regardless of the operation to be performed, the right-hand jaw normally stands in its fully retracted or rightmost position as determined by a banking stop C²⁹ screwed to the jaw support or slide C³ (Fig. 6) since, upon its ascent to operative position, it must clear the terminal end of the composed line. The lug C²⁷ thereon must also clear the associated stop E when the latter is set in its rightmost or full line position (Fig. 6). Upon the inauguration of the casting cycle, brought about by the upward movement of the right-hand jaw, the latter is urged leftward to its casting position, which will be determined by the line if the operation is one of free quadding with the right-hand jaw, or by the jaw stop E if a right-hand indentation or a line of full measure is desired.

For free quadding left, or for centering, the left-hand jaw, before the casting cycle is inaugurated, stands in its leftmost position as determined by a banking stop C³⁰ secured to the vise frame at the left (Fig. 6), the jaw being moved inwardly to casting position as determined by contact with the line and outwardly away from the line by the alternate reversal of the charges

in its pneumatic operating device, as in the case of the right-hand jaw. However, for fixed indentation with the left-hand jaw, or when casting lines of full measure, there is no necessity for the left-hand jaw to move away from its stop E¹ which determines its casting position. Consequently, to avoid wear, means are provided for coupling the jaw to its stop under such conditions. As shown best in Figs. 2, 3 and 8, the stop rack E³ associated with the left-hand jaw C is formed, adjacent its rear face, with a portion E⁴⁵ extending below the rack and to the left of the stop. The portion E⁴⁵ presents a channel E⁴⁶ in which a pawl E⁴⁷ is pivotally mounted on a fore-and-aft pivot pin E⁴⁸, the pivot pin extending through the pawl and being anchored at its ends in the channel walls. At its right end, the pawl E⁴⁷ is formed with a concentric rounded edge which allows the pawl to drop by gravity behind or into engagement with the left face of the lug C²⁸ on the left-hand jaw when the lug is in contact with the stop E¹. Incidentally, the left face of the lug C²⁸ is rounded off to conform to the adjacent surface of the pawl. In its lower edge, the pawl E⁴⁷ is cut away to present a surface E⁴⁹ which rests upon the base of the channel E⁴⁶ when the pawl is in its active position. It will also be noted that the pawl is formed with an enlarged portion E⁵⁰ at its left end to insure its gravity operation. Under those conditions which require the services of the stop E¹, i. e., for fixed indentation at the left or for full line measure, the pawl acts to hold the jaw C against the tendency of its pneumatic operating device to move it outwardly away from the stop. The pawl also serves to couple the jaw to the stop during the manual adjustment of the latter. Under those conditions of machine operation which do not require the services of the stop E¹, i. e., for free quadding with the left-hand jaw or for centering, the pawl E⁴⁷ is disabled, thus permitting the jaw to move free of the stop. The pawl disabling means is referred to later on at a more convenient point.

The right-hand jaw C is moved toward and away from the composed line before and after casting, respectively, by mechanism which includes a vertical rotatable shaft F on which there is mounted a pinion F¹ meshing with rack teeth C³¹ formed in the front face of the jaw throughout its entire length (Figs. 2, 4 and 6). The pinion F¹ remains engaged with the jaw at all times, travelling up and down along the shaft F throughout the ascent and descent of the jaw. For this purpose, the pinion is formed at the bottom with a reduced circular portion or collar F² rotatably mounted in a bearing bracket F³ extending from and formed integrally with the movable jaw support C³. The larger or upper portion of the pinion presents an annular shoulder F⁴ which bears upon the underlying support so that, as the jaw support moves upwardly, the pinion will travel with it. The pinion is constrained to move downwardly with the jaw support by an overlying angular shaped keeper plate F⁵ having a horizontal leg engaging the pinion F¹ at the top and a vertical leg screwed to the bearing bracket F³.

The pinion F¹ is connected for rotation by the vertical shaft F by a series of four splines F⁶ spaced apart at intervals of 90° and which project into vertical grooves F⁷ formed in the pinion hub and also into registering vertical slots F⁸ extending longitudinally of the shaft, the slots F⁸ being of sufficient length to accommodate the

full vertical movement of the jaw support (Figs. 4, 5 and 6). In a word, the arrangement is such that the pinion F¹ will move upwardly and downwardly along the shaft F as the right-hand jaw C moves from its inoperative to its operative position and back again, remaining at all times in engagement with the jaw, so that, as the shaft F is rotated, the jaw will move inwardly to casting position or outwardly to its normal position according to the direction of rotation.

The vertical shaft F is rotated to cause the to and fro movement of the right-hand jaw C by means of a pneumatic device F⁹ consisting of a pair of cylinders F¹⁰ and F¹¹, formed in a single cylinder block mounted on a horizontal shelf B⁸ forming part of the vise frame B, and a pair of pistons F¹² and F¹³, arranged to reciprocate in the cylinders, the latter being located so that the piston movement will be in a fore-and-aft direction (Figs. 4 and 9). The pistons F¹² and F¹³ are provided with piston rods F¹⁴ and F¹⁵ cut to a half round section for the major portion of their lengths and presenting rack teeth which engage diametrically opposed portions of a pinion F¹⁶ fixed to the vertical shaft F just above the vise frame shelf B⁸. The pinion F¹⁶ is formed with an integral collar F¹⁷, the lower face of which rests upon the shelf B⁸ and thus constitutes a thrust bearing for the vertical shaft F. Incidentally, the lower end of the shaft F is journalled in a boss F¹⁸ projecting downwardly from the bottom of the shelf B⁸, the upper end of the shaft being journalled in the vise frame.

At their front ends, the cylinders F¹⁰ and F¹¹ are provided each with an angle member F¹⁹ by which the piston rod is guided, one leg of the angle piece being formed with a boss extending for a short distance within the cylinder to preserve proper alignment, and the other leg presenting a slide bearing engaging the half round face of the piston rod to counteract the lateral thrust on the latter when the machine is operated (Fig. 9). In the rear end walls of the cylinders F¹⁰ and F¹¹, there are provided ducts F²⁰ and F²¹ which are connected through pipe lines F²² and F²³ with a slide valve F²⁴ arranged in a manifold D³, which is common to a number of other slide valves operating different machine organs (Fig. 16). The pipe lines F²² and F²³ are readily traceable in the diagrammatic view of Fig. 26. The pipe line F²² leading from the cylinder F¹⁰ is connected at one end of the slide valve F²⁴ through a T-connection F²⁵, whereas the pipe line F²³ leading from the cylinder F¹¹ is connected at the other end of the slide valve through a T-connection F²⁶. The arrangement is such that when the valve is in one position of adjustment, the cylinder F¹⁰ will be charged with air under pressure and the cylinder F¹¹ vented, whereas when the valve is shifted to its other position of adjustment, the air conditions in the cylinders are reversed. The valve F²⁴ is shifted to its different positions of adjustment under the control of a cam D⁴, mounted on the shaft D, through the medium of a swivel bar F²⁷ and a bell crank lever F²⁸, the latter having one arm bifurcated for connection with the swivel bar and another arm presenting a cam follower F²⁹ constrained to track along the edge cam D⁴ (Fig. 16).

The configuration of the cam D⁴ is such that, when the cam shaft D is at rest, the valve F²⁴ controlled thereby will be adjusted to charge the right-hand cylinder F¹⁰ and vent the left-hand

cylinder F^{11} to the atmosphere. Under such conditions, the piston F^{12} in the cylinder F^{10} will be in its forward position, whereas the piston F^{13} in the cylinder F^{11} will be in its rearward position, as a result of which the right-hand jaw C, which is operated by the pistons through the connections previously described, will be in its normal or right-most position (Fig. 9). However, as soon as the right-hand jaw ascends to its upper operative position, and inauguates the machine cycle, the cam D^4 will adjust the valve F^{24} to reverse the air conditions in the cylinders F^{10} and F^{11} , i. e., the right-hand cylinder F^{10} is vented to the atmosphere and the left-hand cylinder F^{11} charged, with the result that the piston F^{13} moves forwardly and causes the vertical shaft F to rotate in a counterclockwise direction, looking at the parts from the top, thereby moving the right-hand jaw C inwardly until it is arrested by the engagement of its lug C^{27} with the stop E or by direct engagement with the line, as the case may be. The forward movement of the piston F^{13} is accompanied by a corresponding rearward movement of the piston F^{12} , since the pistons are interconnected by the common pinion F^{16} .

The left-hand jaw C¹ is urged toward and away from the composed line before and after casting respectively by mechanism which includes a vertical rotatable shaft F^{30} journalled at its upper end in a fixed portion of the vise frame B and at its lower end in a bearing presented by the fixed vise frame shelf B⁸ and a boss F³¹ depending therefrom (Figs. 3 and 6). At the upper end of the shaft F^{30} , there is mounted a pinion F^{32} meshing with rack teeth C³² formed in the front face of the left-hand jaw and, near the lower end of the shaft, just above the vise frame shelf B⁸, there is mounted another pinion F^{33} cooperating at diametrically opposed points with rack teeth presented by a pair of piston rods F^{34} and F^{35} (Figs. 9 and 10). The piston rods F^{34} and F^{35} are secured to pistons F^{36} and F^{37} arranged to reciprocate in a pair of cylinders F^{38} and F^{39} , the two cylinders and pistons constituting a pneumatic device for operating the left-hand jaw in opposite directions. The pneumatic device just described is the same in all respects as the corresponding device for operating the right-hand jaw, except that the cylinders F^{38} and F^{39} are mounted on the vise frame shelf B⁸ at right angles to the cylinders F^{10} and F^{11} (Figs. 9 and 10). Not only is the construction of the pneumatic devices the same but, indeed, the control valve F^{24} is common to both. That is, the end walls of the cylinder F^{38} and F^{39} are formed with ducts F^{40} and F^{41} communicating with the valve F^{24} through pipe lines F^{42} and F^{43} which include respectively, the T-connections F^{25} and F^{26} in the pipe lines F^{22} and F^{23} leading to the cylinders F^{10} and F^{11} . Consequently, when the machine is at rest and the valve F^{24} is set to charge the cylinder F^{10} associated with the right-hand jaw, the cylinder F^{38} associated with the left-hand jaw is likewise charged, so that the forces acting will tend to urge the jaws apart; whereas, when the valve is set to charge the cylinder F^{11} associated with the right-hand jaw, the cylinder F^{39} associated with the left-hand jaw will be charged also, and the forces then acting will tend to move the jaws inwardly toward each other. After the slug casting operation has been completed, the vise jaw cam D^4 acts again to shift the valve F^{24} and reverse the air conditions in the cylinders

i. e., the cylinders F^{10} and F^{38} associated with the right and left-hand jaws, respectively, will be charged with air pressure and the associated cylinders F^{11} and F^{39} vented to the atmosphere. Under such conditions, the right-hand jaw will be moved to its outer or normal position as has been described. A corresponding outward movement of the left-hand jaw will take place only when the machine is set for free quadding with the left-hand jaw and for centering since, under all other conditions, the pawl E^{47} acts to hold the left-hand jaw against outward movement away from the stop E¹.

The hydraulic jaw clamping mechanism

While other means might be used, the instant machine utilizes hydraulic mechanism for exerting a clamping pressure on the jaws to insure a tight line during the slug casting operation. Referring to Figs. 3, 4, 12 and 13, it will be observed that immediately below the vise frame shelf B⁸ which supports the vise jaw operating cylinders F^{10} , F^{11} , F^{38} and F^{39} , there is provided a closed compartment G filled with oil or other suitable liquid. Within the compartment there is mounted a casting G¹ secured to the shelf at the bottom and formed with two cylinders G² and G³ disposed at right angles, the cylinder G² being parallel to the air cylinders F^{10} , F^{11} operating the right-hand jaw, and the cylinder G³ parallel to the air cylinders F^{38} and F^{39} operating the left-hand jaw. Arranged to reciprocate within the cylinders G² and G³ are pistons G⁴ and G⁵ provided with piston rods G⁶ and G⁷ formed with rack teeth, the teeth on the piston rod G⁶ engaging a pinion G⁸ fixed to the lower end of the vertical shaft F which operates the right-hand jaw C, and the teeth on the piston rod G⁷ engaging a pinion G⁹ fixed to the lower end of the vertical shaft F³⁰ which operates the left-hand jaw C¹. The ends of the cylinders G² and G³, adjacent the pinions, open into the oil compartment G so that the liquid can readily flow into and out of those ends of the cylinders, although the cylinders at said ends are formed with slide bearings G¹⁰ to buttress the piston rods against lateral thrust. At their opposite ends, the cylinders G² and G³ are closed by relatively strong cylinder heads G¹¹ so that a substantial pressure can be built up between said heads and the adjacent pistons G⁴, G⁵.

The cylinder casting G¹ is formed with a pair of vertical cylindrical recesses G¹² and G¹³ disposed one behind the other in a fore-and-aft plane. The bottom of the rear recess G¹² is connected by a duct G¹⁴ with the cylinder G² associated with the right-hand jaw, the duct entering the cylinder adjacent its head and at the rear of the piston. The front cylindrical recess G¹³ is similarly connected to the cylinder G³ associated with the left-hand jaw by a duct G¹⁵. The cylindrical recesses G¹², G¹³ contain, respectively, plungers G¹⁶ and G¹⁷ arranged for limited vertical movement therein. The plungers extend upwardly through the vise frame shelf B⁸ and, when they are in their raised or normal positions, they uncover ports G¹⁸ and G¹⁹ which establish communication between the main compartment G, on the one hand, and the cylinders G² and G³, on the other hand, through the ducts G¹⁴ and G¹⁵ (Figs. 12 and 13). The plungers are notched near their upper ends to accommodate the rounded end portions of a pair of bell crank levers G²⁰ and G²¹, pivotally mounted on a fore-and-aft bearing rod G²² supported at its rear end in a vertical portion of the vise frame B (Figs. 3, 9 and

13). The bell crank levers G^{20} and G^{21} are formed with depending arm portions connected at their lower ends through links G^{23} to a pair of long powerful springs G^{24} and G^{25} , which extend horizontally to the left and are anchored at their opposite ends to a pin G^{26} fixed in the vise frame. The bearing rod G^{22} also pivotally supports another pair of lever members G^{27} and G^{28} arranged one adjacent each of the bell crank levers and formed each with an arm presenting a laterally extending lip G^{29} which overlies that arm of the associated bell crank lever connected with the plunger G^{16} or G^{17} , as the case may be. The lever members G^{27} and G^{28} also have depending arm portions connected at their lower ends to a pair of tension springs G^{30} and G^{31} which extend upwardly and are anchored at their upper ends to a pin G^{32} fixed in the vise frame. The springs G^{30} and G^{31} are somewhat lighter than the horizontal springs G^{24} and G^{25} and are capable of being selectively disabled under certain conditions which will be referred to later on.

Normally, the plungers G^{16} and G^{17} are held in their raised positions, against the combined pull of their respective pairs of springs, by a lever G^{33} pivotally mounted adjacent its center on a short fore-and-aft bearing rod G^{34} supported at its rear end in the vise frame somewhat below the bearing rod G^{22} (Figs. 3 and 12). The lever G^{33} is formed at its upper end with a T-shaped head G^{35} wide enough to engage bearing surfaces presented by both the bell crank levers G^{20} , G^{21} and also by both the adjacent associated lever members G^{27} and G^{28} . At its lower end, the lever carries an anti-friction roller G^{36} arranged to track along an edge cam D^5 mounted on the cam shaft D . The cam configuration is such that when the machine is at rest, the plungers are held in their raised positions against the reaction of the springs G^{24} , G^{30} , G^{25} , G^{31} , which tend to move them downwardly.

Whatever motion is imparted to the vise jaws C , C^1 , either in moving them against their stops E , E^1 or against the line, will be accompanied by a corresponding movement of the associated pistons G^4 and G^5 in the hydraulic cylinders, since the jaws and their respective pistons are operated from the same vertical shafts. The piston movement will not retard the jaw movement to any great extent, since the pistons are formed each with a pair of horizontal ports G^{37} to allow the liquid to flow freely from the front to the back of the pistons as they move outwardly (Figs. 13 and 14). The ports in each piston are covered by a flap valve G^{38} fastened at its upper end to the piston by a screw G^{39} having an enlarged portion on which the flap is slidably mounted and a head G^{40} sufficiently spaced from the piston face to allow the flap a limited movement away from the piston face to uncover the ports. The flap is guided in its movement toward and away from the face of the piston by a horizontal pin G^{41} projecting from the piston and which passes through a hole in the flap. A light pressure spring G^{42} , reacting between the head G^{40} of the screw and the flap G^{38} , tends to hold the flap in its normal closed position, although the spring will present little resistance to the opening of the flap by the liquid flow during the outward movement of the piston (Fig. 14). Then, too, the liquid will flow through the ports G^{18} , G^{19} beneath the plungers G^{16} , G^{17} during the outward movement of the pistons, so that when the jaws are brought to rest, the cylinders at the rear of the pistons will be filled with liquid.

Immediately after the jaws have been located in their line clamping positions, a drop D^6 in the hydraulic plunger cam D^5 permits the lever D^3 to turn counterclockwise, looking at the parts 5 from the front, thus freeing the bell crank levers G^{20} and G^{21} and their associated members G^{27} and G^{28} and permitting the plungers G^{16} and G^{17} to be forced downwardly under the action of their associated springs.

- 10 Under all conditions of operation, except free quadding with one jaw, the plungers are forced downwardly under the combined action of their respective light and heavy springs. In the excepted condition, the light spring associated with 15 the free quadding jaw is locked out of action, so that the line clamping pressure exerted by that jaw will be due solely to its associated heavy spring. The reason for this and the means by which it is accomplished are set forth later on.
- 20 As the plungers G^{16} and G^{17} move downwardly, they close off the underlying ports G^{18} and G^{19} , so that the force of the active springs will be exerted through the liquid upon the pistons, and consequently upon the vise jaws, multiplied through the 25 intermediate connections previously described. Of course, when the liquid in the hydraulic cylinders at the rear of the pistons is under pressure, the flap valves G^{38} are held closed by said pressure, otherwise it would be impossible for the pressure to build up.

The hydraulic units that have just been described are somewhat in the nature of hydraulic racks except for the supplemental plunger action by which the liquid in the cylinders is placed 35 under pressure. Were it merely a question of locating the jaws in a predetermined clamping position by means of their stops E and E^1 and relying upon the justification of the spacebands to produce a tight line, true hydraulic racks could 40 be employed. However, since the machine is designed for free quadding with either jaw and for centering, such conditions make it desirable to produce a line squeeze because of the probable absence of spacebands in the line. The plunger 45 action will produce the necessary line squeeze in such cases.

As in the commercial linotype machine, line justification in the instant machine occurs in two stages, commonly termed first and second justification, between which matrix alignment takes 50 place. The mechanism for effecting matrix alignment has been fully described in copending application Serial No. 377,364. The hydraulic pressure is initially exerted upon the jaws before the first stage of justification, otherwise there 55 would not be sufficient reaction at the ends of the line to resist the expanding action of the wedge shaped spacebands. However, after first justification, it is desirable to relieve the clamping pressure on the line in order to facilitate the 60 matrix alignment operation. The clamping pressure is relieved by raising the plungers G^{16} , G^{17} to open the ports G^{18} and G^{19} , thus allowing the jaws to retreat to whatever extent is necessary to 65 relieve the internal pressure in the matrix line. The plungers are raised by rocking the lever G^{33} back to its normal position, thereby turning the bell crank levers G^{20} and G^{21} against the reaction of the tension springs G^{24} , G^{25} , G^{30} , G^{31} , in a direction to lift the plungers. The lever G^{33} is rocked in the manner stated under the control of the hydraulic plunger cam D^5 which is formed with a high portion D^7 located to cooperate with the roller D^3 on the lever after first justification has taken 70 place and immediately preceding matrix align- 75

ment. In Fig. 22, the parts are shown just as the roller D³⁶ is about to ride up on the high portion D⁷ of the cam.

Because of the spring reaction that has to be overcome in raising the plungers G¹⁶, G¹⁷ to relieve the clamping pressure, pneumatic mechanism is provided to assist the cam D⁵ in rocking the lever G³³ in order that all of the required force will not have to be exerted through the cam and the cam shaft D, which are relatively light (Fig. 22). This mechanism is located below the cam assembly and includes a cylinder G⁴³ formed at the bottom with a lug G⁴⁴ through which there passes a fore-and-aft supporting shaft G⁴⁵ mounted at its ends in fixed portions of the vise frame B (see also Figs. 1 and 3). There is arranged to reciprocate within the cylinder G⁴³, a piston G⁴⁶ provided with a piston rod G⁴⁷ guided in its reciprocating movement by the cylinder head through which it extends. At its upper end, the piston rod G⁴⁷ is pivotally connected to an arm G⁴⁸ offset from the lower arm of the lever G³³. The cylinder below the piston is connected by a pipe line G⁴⁹ to a valve G⁵⁰ in the air manifold D³ (Figs. 22 and 26), the valve being adjustable by a swivel bar G⁵¹ which, in turn, is rocked from one position to another by a small pivotally mounted bell crank lever G⁵² and which has one arm bifurcated to engage the end of the swivel bar G⁵¹. A cam roller G⁵³, mounted at the end of the other arm of the bell crank lever, tracks along an edge cam D⁸ (Fig. 16). The cylinder and piston mechanism is one way acting and, in the normal position of the parts, the valve G⁵⁰ is adjusted to vent the cylinder to the atmosphere. However, just as the cam roller on the lever G³³, which controls the operation of the plungers G¹⁶, G¹⁷, is about to ride up on the high portion D⁷ of its control cam D⁵, a high portion D⁹ on the cam D⁸ rocks the bell crank lever G⁵² to adjust the valve G⁵⁰ to admit air under pressure into the cylinder G⁴³ (Fig. 22). The result is that substantially all of the force required to rock the lever G³³ against the reaction of the springs G²⁴, G²⁵, G³⁰, G³¹ is exerted by the pneumatic mechanism. A portion of the force required to rock the lever G³³ is exerted by the cam D⁵ itself since, if the pneumatic mechanism overcomes the entire spring reaction, the hydraulic plunger cam D⁵ would lose its timing function.

When the cam roller G³⁶ reaches the high portion D⁷ of the hydraulic plunger cam D⁵, the cam roller G⁵³ on the lever G⁵² which controls the valve G⁵⁰ rides off the high portion D⁹ of its control cam D⁸, thereby adjusting the valve to vent the cylinder D⁴³. Consequently, when the cam roller G³⁶ drops off the high portion D⁷ of the hydraulic plunger cam after the brief period required to permit matrix alignment and just prior to second justification, the springs G²⁴, G²⁵, G³⁰ and G³¹ will be free to act as they did prior to first justification, that is to say, they will force the plungers G¹⁶ and G¹⁷ downwardly to reestablish the clamping pressure on the line.

Subsequent to the actual slug casting operation, the clamping pressure is relieved to permit the retraction of the right-hand jaw and the left-hand jaw. At that time, another high portion D¹⁰ on the hydraulic pressure relief cam D⁸ effects the adjustment of the valve G⁵⁰ to charge the cylinder G⁴³ again, just as the cam follower G³⁶ on the plunger operating lever G³³ starts to mount a second high portion D³³ on the hydraulic plunger cam D⁵. The operations previously described are now repeated, i. e., the plung-

ers G¹⁶ and G¹⁷ are raised to relieve the pressure on the jaws for the purpose mentioned.

It is pointed out that the leading edges of both high portions D⁷ and D¹¹ on the hydraulic plunger cam D⁵ rise gradually in order that, in each instance, the clamping pressure on the line will be gradually released, thus preventing any tendency for the line to explode as might occur if the pressure were relieved abruptly. It should also be noted that the thrust of the piston rod G⁴⁷ acts substantially at right angles to a line drawn through its pivotal connection with the arm G⁴⁸ and the axis of the bearing rod G³⁴ which supports the lever G³³, thereby giving the maximum in mechanical advantage. The arrangement necessitates locating the piston rod between two of the cams of the cam assembly (Figs. 3 and 22) and, for this reason, the piston rod in its upper portion is formed flat to provide the necessary clearance.

It may also be stated at this point that, when the hydraulic pistons G⁴ and G⁵ move inwardly in their cylinders G² and G³ in synchronism with the outward movement of the jaws C and C¹ after the casting operation, the liquid will flow from the cylinders through the passageways G¹⁴ and G¹⁵ and through the ports G¹⁸ and G¹⁹ into the outer liquid compartment G, the plungers G¹⁶ and G¹⁷ at the time being in their raised positions uncovering said ports.

The pneumatic justifying mechanism

In the instant machine, the composed line is justified by a horizontal bar H which is pushed upwardly against the lower ends of the wedge shaped spacebands, causing the line to spread out to fill up the space between the line clamping jaws C and C¹ when the active positions of the latter are determined by their respective stops E and E¹ (Fig. 3).

The action of the justification bar H upon the spacebands is somewhat different from that in the standard linotype machine. For one thing, the bar maintains a horizontal position at all times and between first and second justification, it remains in the position it reached during the first justifying operation. Furthermore, the force exerted upon the spacebands is substantially less during the first justifying stage than during the second.

The justification bar or spaceband driver H is formed at the upper end of a vertical slide H¹ provided in its lateral edges with tongues H² guided in grooves H³ presented by a fixed portion of the vise frame B at the rear thereof (Figs. 2, 3 and 16). The bar is pneumatically operated in both directions, i. e., upwardly and downwardly, the vertical slide for this purpose being connected adjacent its lower end at the top of a piston rod H⁴ forming part of a pneumatically operated double-acting cylinder and piston device vertically disposed on a fixed portion of the vise frame B near the bottom. The pneumatic device further includes a cylinder H⁵ which, adjacent its upper end, that is, above the piston, is connected through a pipe line H⁶ with a slide valve H⁷ located in the manifold D³ (Figs. 16, 23 and 26). The valve H⁷, like those previously mentioned, is adjusted to its different positions by means of a swivel bar H⁸ connected with the bifurcated end of one arm of a pivotally mounted bell crank lever H⁹ which is formed with a second arm presenting a cam follower H¹⁰ constrained to track along an edge cam D¹¹ mounted on the cam shaft D (Fig. 16).

Below its piston, the cylinder H^5 is likewise connected with the valve H^7 through a pipe line H^{11} which contains a reducing valve H^{12} to which further reference will be made later on. As indicated by the arrows in Fig. 26, the valve H^7 is normally set to charge the justification cylinder H^5 at the top and vent the bottom thereof to the atmosphere. Under such conditions, the justification bar H remains in its lowermost position below the bottom ends of the unexpanded spacebands and in line with the right-hand jaw C in its normal position. The justification bar, at its right end and the jaw, at its left end are formed respectively with a tongue h , and a groove C^4 which cooperate to provide the necessary overlap without interference. At the proper stage in the machine cycle, i. e., after the line clamping pressure has been initially applied the cam follower H^{10} rides up on a high portion D^{12} of the justification cylinder cam D^{11} , thereby adjusting the valve H^7 to vent the cylinder H^5 at the top and to allow air under pressure to flow to the bottom of the cylinder through the pipe line H^{11} which contains the reducing valve H^{12} (Figs. 23, 24 and 25). The result is that the bar H ascends, driving the spacebands upwardly to justify the line.

Thereafter, the cam follower H^{10} rides off the high portion D^{12} of the cam D^{11} to a somewhat lower portion D^{13} , causing the valve H^7 to be adjusted to a neutral position, closing the air off from both ends of the cylinder. When the valve is in its neutral setting, the justification bar H remains stationary, exerting no pressure, until a second high portion D^{14} on the cam D^{11} arrives opposite the follower H^{10} , causing the valve H^7 again to be adjusted to the position permitting air to flow under pressure to the lower end of the cylinder to effect the second justification operation. It is during that period when the justification bar remains stationary that the clamping pressure on the line is relieved, the matrix alignment effected and the clamping pressure reapplied. When the cam follower rides off the second high portion D^{14} of the cam, the valve H^7 is again adjusted to a neutral position, and later on back to its original position to charge the justification cylinder at the top and restore the justification bar to its normal lowermost position. The configuration of the cam D^{11} is such as to accomplish these functions (Fig. 23).

As previously stated, first and second justification are carried out under different pressures, the air passing from the manifold D^3 to the lower end of the justification cylinder H^5 through the pressure regulating valve H^{12} illustrated in detail in Figs. 23, 24 and 25. The valve H^{12} is formed in two units H^{13} and H^{14} , the upper unit H^{13} being fixed to a bracket B^9 on the vise frame B , and the lower unit H^{14} being pivotally mounted on said bracket. The upper unit consists of a top portion H^{15} and a lower portion H^{16} screwed together, both portions being hollowed out to present two cylindrical chambers H^{17} and H^{18} which are separated by a horizontal flexible diaphragm H^{19} securely anchored around its peripheral edge where the two portions of the upper unit are connected together. A reduced vertical passageway H^{20} connects the upper chamber H^{17} with an overlying chamber H^{21} which is closed at the top by a threaded cap H^{22} . A vertical rod H^{23} , constituting a valve stem, is guided at its upper end for limited vertical movement by a bushing H^{24} , recessed into the base of the cap element, and is connected at its lower end to a relatively large

disk H^{25} which seats upon the top of the flexible diaphragm H^{19} . About midway of its length, the valve stem is formed with an enlarged portion H^{26} constituting a valve adapted to cooperate with an underlying valve seat located at the base of the upper chamber H^{21} , i. e., where said chamber and the passageway H^{20} communicating with the chamber H^{17} intersect. A spring H^{27} , encircling the valve stem and reacting between the cap H^{22} and the enlarged valve portion H^{26} , acts to hold the disk H^{25} in engagement with the flexible diaphragm so that the latter will control the movement of the valve stem. The portion of the airline H^{11} which connects with the control valve H^7 opens into the upper chamber H^{21} , or the chamber above the valve seat, whereas the portion of the airline H^{11} which is connected to the justification cylinder at its lower end opens into the cylindrical chamber H^{17} which is above the diaphragm but below the valve seat.

The lower unit H^{14} of the pressure regulating valve is formed with a laterally extending arm H^{28} pivotally mounted about midway of its length on the fixed bracket B^9 and presenting at its outer end a cam follower H^{29} arranged to track along a cam D^{34} (Fig. 16). The lower valve unit H^{14} is adapted to be rocked from its normal or solid line position shown in Fig. 23, which is determined by a banking screw h^1 threaded into the bracket B^9 at its lower end, to the dotted line position shown in that figure, the different positions of the valve unit being determined by concentric high and low portions D^{15} and D^{16} of the cam D^{14} (Fig. 23).

The lower valve unit H^{14} is hollowed out to present a vertical cylindrical chamber H^{30} having a bottom closing member H^{31} through which there extends a vertical rod H^{32} , provided at its lower end with a handle or knob H^{33} pinned thereto. The rod H^{32} is adjustably threaded into the bottom closing member H^{31} . At the upper end of the rod H^{32} , there is mounted a circular element H^{34} , the outer surface of which is in sliding engagement with the inner walls of the cylindrical chamber H^{30} . The circular element H^{34} acts as a lower abutment for two concentrically located compression springs H^{35} and H^{36} . The outer spring H^{35} , which is stronger than the inner spring H^{36} , reacts against the bottom of an annular member H^{37} slidably fitted within the cylindrical chamber H^{30} and pushes the member upwardly into engagement with an annular shoulder H^{38} presented at a point where the chamber is reduced in size.

The lower valve unit is further provided with a stem H^{39} located in axial alignment with the cylindrical chamber H^{30} and which has four longitudinally spaced portions H^{40} , H^{41} , H^{42} , H^{43} , having diameters of different sizes, the lowest portion H^{40} , which is the smallest, being encircled by the lighter spring H^{36} which, at its upper end, reacts against a shoulder presented by the adjacent portion H^{41} of the stem which is of larger diameter. This second portion H^{41} of the stem is slidably within the annular member H^{37} against which the larger spring H^{35} reacts. The immediately overlying portion H^{42} of the stem is in sliding engagement with the reduced portion of the cylindrical chamber, whereas the upper portion H^{43} of the stem extends through a hole H^{44} formed in the upper end of the valve unit. The diameter of the hole H^{44} is smaller than the diameter of the reduced chamber portion in order to present a shoulder H^{45} which serves as an overlying abutment for the largest portion H^{42} of

the stem and against which the stem is pressed by the smaller spring H³⁶.

The portion H⁴³ of the stem H³⁹ which extends through the hole H⁴⁴ in the top of the valve unit engages at its top against the lower end of an overlying stem H⁴⁶ which projects through the base of the upper valve unit H¹³ and into the chamber H¹⁸ below the flexible diaphragm H¹⁹, the upper end of said stem being provided with a relatively large flat disk H⁴⁷ which presses against the under surface of the diaphragm in opposition to the disk H²⁵ which presses down on it from above. When the parts are in their normal positions, i. e., when the stem portion H⁴² seats against the shoulder H⁴⁵, the diaphragm H¹⁹ is flexed to hold open the valve H²⁶.

According to the arrangement just described, when the control valve H⁷ is adjusted to charge the lower end of the justification cylinder H⁶ for the first justifying operation, the air passes through one section of the pipe line H¹¹ into the top chamber H²¹ of the regulating valve H¹², through the passageway H²⁰ into the chamber H¹⁷ above the diaphragm, and thence out through the other section of the pipe line H¹¹ to the justification cylinder. As the pressure builds up, the justification bar H rises to drive the spacebands up through the line against ever increasing resistance until the pressure in the justification cylinder and, consequently in the chamber H¹⁷ above the diaphragm, reaches a point sufficient to overcome the reaction of the smaller spring H³⁶ in the lower valve unit H¹⁴. Thereupon the diaphragm will push the stem H³⁹ down until the largest portion H⁴¹ thereof seats against the annular member H³⁷. The distance through which the stem H³⁹ moves at this time is sufficient to permit the valve H²⁶ in the upper valve unit H¹³ to seat under the reaction of its associated spring H²⁷, thereby preventing any further passage of air into the justification cylinder. Thereafter, as will be recalled, the control valve H⁷ is adjusted to a neutral position. When the valve H⁷ is in neutral position, the upper chamber H²¹ in the pressure regulating valve is vented to the atmosphere, as is also the top of the justification cylinder. As the pressure in the chamber H²¹ drops, the valve H²⁶ opens and vents the lower end of the justification cylinder, with the result that the justification bar remains in the position it reached during first justification. The valve H²⁶ opens under the action of the smaller spring H³⁶ as soon as the pressure conditions become unbalanced due to the reduction in air pressure above the valve H²⁶. During the interval between first and second justification when the control valve H⁷ is adjusted to neutral, the high portion D¹⁵ of the valve cam D¹⁴ engages the cam follower H²⁹ and swings the lower valve unit H¹⁴ to the dotted line position shown in Fig. 23. This has the effect of moving the lower valve housing upwardly with respect to the valve stem H³⁹ and against the reaction of the smaller spring H³⁶, the parts assuming the relative positions shown in Fig. 25 with the enlarged portion H⁴² of the valve stem seating on the annular member H³⁷ which, as will be recalled, is held upwardly by the reaction of the larger spring H³⁵.

Now, when the control valve H⁷ is again adjusted to effect the second justifying operation, air will flow through the pressure regulating valve H¹² as before. This time, however, the upper valve H²⁶ will not close until the resistance offered to the expanding action of the spacebands is sufficient to cause the pressure in the

justification cylinder and in the chamber H¹⁷ above the diaphragm H¹⁹ to build to a point high enough to overcome the combined reaction of both the light and heavy springs H³⁵ and H³⁶ in the lower valve unit. When that pressure is reached, the diaphragm H¹⁹ will push the stem H³⁹ downwardly against the reaction of said springs to a point permitting the valve H²⁶ to close again and cut off the further supply of air. 5 After second justification, the control valve H⁷ is adjusted back to neutral position and permits the valve H²⁶ to open as before and vent the lower end of the justification cylinder, thereby relieving the upward thrust on the spacebands during 10 casting. Later on in the machine cycle, the cam follower H²⁹ rides off the high portion D¹⁵ of the cam D¹⁴, permitting the lower valve unit H¹⁴ to be restored to its normal position. At approximately the same time, the control valve H⁷ is 15 adjusted from neutral position to charge the justification cylinder at the top and restore the justification bar H to its normal lowermost position.

20 Since the pressures effective during justification depend entirely upon the forces exerted by the springs H³⁵ and H³⁶, the present mechanism furnishes a ready means for varying those pressures as desired. For instance, if the operator is casting from a line 15 ems in length, it will not be necessary for the justification pressures to be 25 as high as when casting from a line 30 ems in length, since the average number of spacebands in lines of 15 ems will be about half the average number of spacebands in lines of 30 ems. The 30 justification pressures are regulated by turning the threaded shaft H³² to move the abutment member H³⁴ up or down so as to regulate the compression of the springs H³⁵ and H³⁶ to the degree desired. The shaft H³² is adjusted by means 35 of the knob H³³ to which it is attached, and the degree of adjustment is indicated by a scale H⁴⁹ on the unit H¹⁴ in conjunction with the top edge of the knob which is bevelled to facilitate the 40 scale reading.

The machine conditioning means

The machine is conditioned for its various operations by a manually adjustable disk J located at the front of the machine within convenient 45 reach of the operator and rotatably mounted on a screw bolt J¹ which passes through the disk and is threaded into a fixed portion of the vise frame (Figs. 1 and 9). A handle J² formed integrally with the disk enables it to be adjusted to 50 one or another of four different settings indicated by notches J³ in the edge of a fixed plate J⁴ encircling the disk. The disk J is maintained in its 55 different settings by a spring-pressed detent J⁵ which enters the notch corresponding to the setting (Fig. 11), the notches being labeled "Reg.," "Q. R.," "Cent." and "Q. L." indicating respectively, regular operation, quadding right, centering, and quadding left.

Immediately behind the adjustable disk, there 60 are mounted two plates J⁶ and J⁷ joined together facewise so as to move vertically as a unit, the unit being guided at its lower end by a pair of spaced lugs J⁸ which engage its lateral faces, as do likewise a pair of similarly functioning lugs J⁹ near its upper end. The lugs J⁸ and J⁹ are 65 formed on a bracket J¹⁰ which presents a guiding surface for the rear edge of the plate unit, a front guide being presented by the adjustable disk J and the adjacent surfaces of the plate J⁴. In a word, the unit consisting of the plates J⁶

and J^7 is constrained to move only in a vertical direction (see Figs. 2, 3 and 9).

The vertical adjustment of the plate unit J^6 , J^7 is effected by the rotary adjustment of the disk J , the unit in turn effecting automatically the various adjustments that must be made to the different mechanisms to enable them to carry out the operation indicated by the disk setting. The plate unit is connected for adjustment by the disk J through the medium of a pin J^{11} projecting rearwardly from the disk adjacent its peripheral edge and into what in effect is a single notch J^{12} formed in the plate unit. Actually, both plates are formed with notches but since the notches register and since the plates are connected together, it may be considered that the plate unit presents but a single notch as just stated. When the adjusting disk J is set for regular machine operation (Figs. 17 and 19), the plate unit J^6 , J^7 is in its upper position of adjustment, but as the disk is stepped around in a counterclockwise direction to its other positions of adjustment, the plate unit will move downwardly to corresponding positions indicated by the dotted lines appropriately labeled in Fig. 19.

As mentioned previously, when the machine is set for quadding right, the stop E associated with the right-hand jaw C must be disabled. This is accomplished by means of the lever E^{24} which pulls the locking bolt E^4 out of engagement with the stop slide E^2 when it is desired to adjust the stop by means of the elongated pinion E^{20} and the knob E^{18} (Figs. 1 and 18). It will be recalled that the lever E^{24} is pivotally mounted at its lower end. The pivotal mounting consists of a transverse rock shaft J^{13} to which the lever E^{24} is fixed and which is journaled at its right end in a fixed bearing support J^{14} and at its left end in a similar support J^{15} located just above the adjustable plate unit J^6 , J^7 (Fig. 1). At the left end of the rock shaft, there is pinned an arm J^{16} which extends downwardly and is provided at its lower end with a laterally extending pin J^{17} held in engagement with the rear edge of the right-hand slide plate J^6 by the spring E^{17} in the locking bolt E^4 which tends to turn the lever E^{24} , and consequently the rock shaft J^{13} , in a counterclockwise direction looking at the machine from the left. The rear upper edges of the plates J^6 , J^7 constitute cam surfaces and their configurations are clearly shown in Fig. 19. When the machine is set for regular operation, the position of the pin J^{17} with reference to the right-hand plate J^6 is as indicated by the solid line section at z . Now, when the slide J^6 is moved downwardly to the quadding right position, the pin J^{17} is cammed rearwardly by the slide to the position indicated at y , with the result that the arm J^{16} on which the pin is mounted rocks the shaft J^{13} in a direction causing the lever E^{24} to pull the locking bolt E^4 out of engagement with the stop rack E^2 , thereby disabling the stop E . The locking bolt will remain in its inactive position so long as the machine remains set for the quadding right operation.

When the locking bolt is inactive, the right-hand jaw C , upon the inauguration of a machine cycle will move inwardly until it is arrested by engagement with the line rather than by engagement with the stop which, being free to move, is merely pushed to the left by the jaw lug C^7 . Of course, when the machine is again set for regular operation, the stop E associated with the right-hand jaw C will have to be set

manually to its proper position in the manner previously described.

When the plate J^6 is moved downwardly to set the machine for centering, the stop E associated with the right-hand jaw is disabled in the same way as when quadding right, since the pin J^{17} will have the same relative position in a fore-and-aft direction as it has when the plate is adjusted for quadding right. This position is indicated at x in Fig. 19.

When, however, the plate J^6 is moved downwardly to set the machine for quadding left, the pin J^{17} returns to its original position indicated at w in Fig. 19, since the plate is formed with a depression at the point where it engages the pin in that position of adjustment. With the pin J^{17} in the position indicated at w , which indeed is its normal position, the locking bolt E^4 will be active to hold the jaw stop E in a fixed position. Should it be necessary to adjust the position of the stop E when the machine is set for quadding left, such adjustment can be effected in the usual way by means of the knob E^{18} .

The mechanism for disabling the stop E^1 associated with the left-hand jaw C^1 , during centering or quadding left, is somewhat similar to that for disabling the stop E associated with the right-hand jaw C with certain differences, however, necessitated by the presence of the locking pawl E^{47} which normally acts to couple the left-hand jaw with its stop. As shown in Figs. 2, 6 and 8, there is provided a plate J^{18} underlying the locking pawl E^{47} and which is long enough to be engaged by the pawl at its left end in any adjusted position of the left-hand jaw. The plate J^{18} is movable edgewise in a vertical direction, although when it is in its normal or lowermost position, it allows the pawl to locate itself in its active position with the lug C^8 on the jaw and the stop E^1 coupled together, as previously described. However, during quadding with the left-hand jaw and during centering, the plate J^{18} is moved upwardly to the position shown in Fig. 8, thereby swinging the pawl E^{47} to an inactive position and permitting a relative movement between the jaw and its stop. When the pawl is rendered inactive, i. e., when it releases the jaw C^1 , the latter will move outwardly to its leftmost position should it previously have been set for a left-hand indentation, since, as will be recalled, the pneumatic device controlling the operation of the left-hand jaw is normally charged to urge the jaw outwardly.

The plate J^{18} is guided in its vertical movement by a pair of plates J^{19} fixed in the vise frame (Fig. 3) and is moved to its different positions by a pair of spaced arms J^{20} . These arms are connected at their rear ends to the plate J^{18} by swivel socket joints and at their front ends are fixed to a rock shaft J^{21} , which latter is journaled at its left end in a fixed bearing J^{22} and at its right end in the bearing J^{15} , the same as that supporting the rock shaft J^{13} which is active in disabling the stop E associated with the right-hand jaw C (Figs. 1, 2, 3, 6 and 8).

The movement of the rock shaft J^{21} is controlled from the left-hand plate J^7 of the plate unit through an arm J^{23} pinned at its upper end to the rock shaft and provided at its lower end with a pin J^{24} engaging the rear edge of said left-hand plate member (Figs. 17 and 19). The plate member J^7 also, and simultaneously, controls the disabling of the stop E^1 associated with the left-hand jaw C through the same arm J^{23} , which latter for this purpose is provided

with a pin J^{25} extending to the left and which stands in front of an arm J^{26} depending from a hub J^{27} rotatably mounted on the rock shaft J^{21} (Figs. 1 and 17). The lever E^{25} , which controls the engagement and disengagement of the locking bolt E^5 associated with the left-hand jaw stop rack E^3 , is also formed integrally with the hub J^{27} , the rock shaft furnishing the pivotal mounting for the lever E^{25} to which reference has been made. The arrangement is such that, when the arm J^{23} is moved rearwardly to rock the shaft J^{21} and move the plate J^{18} upwardly to disable the pawl E^{47} , it simultaneously rocks the lever E^{25} forwardly to withdraw the locking bolt E^5 out of engagement with its associated rack, thus rendering the left-hand jaw free to move during a quadding or a centering operation as the length of the line demands.

The rear edge of the left-hand control plate J^7 , at the upper portion thereof which cooperates with the pin J^{24} , has a different configuration from the corresponding portion of the right-hand plate which cooperates with the pin J^{17} (Fig. 19). The normal fore-and-aft position of the pin J^{24} with reference to the plate J^7 for regular machine operation is shown at z^1 by the solid line section; whereas its position corresponding to the quadding right, centering and quadding left adjustments of the plate are shown by the dot and dash lines, respectively, at y^1 , x^1 and w^1 . In the normal position z^1 of the pin J^{24} , the stop E^1 associated with the left-hand jaw C is active, as is likewise the pawl E^{47} which holds the jaw against its stop. And when the plate J^7 is moved downwardly to its quadding right adjustment, the pin J^{24} remains undisturbed, the position y^1 being the same as position z^1 . That is, when the machine is adjusted for quadding right, the locking bolt E^5 associated with the left-hand jaw remains active so that the casting position of the jaw is determined by the position of its stop E^1 . However, when the plate J^7 is adjusted for centering or for quadding left, the pin J^{24} is cammed rearwardly, thereby disabling the jaw stop E^1 and the locking pawl E^{47} in the manner previously described. The relative positions of the pin J^{24} with respect to the plate J^7 are indicated respectively at x^1 and w^1 . When the plate J^7 is again adjusted for regular machine operation or for quadding right, the parts will be restored to their normal positions by the lock bolt spring E^{17} , which acts, through the lever E^{25} and its integrally connected arm J^{26} , upon the pin J^{25} projecting from the arm J^{23} pinned to the rock shaft J^{21} .

Permitting the lever E^{25} associated with the left-hand jaw to pivot freely upon the rock shaft J^{21} rather than having it fixed thereto, as in the case of the lever E^{24} and the rock shaft J^{13} associated with the right-hand jaw, permits the manual adjustment of the left-hand jaw without rendering the locking pawl E^{47} inactive. This is desirable, since when conditions permit the left-hand jaw will be adjusted automatically with its stop. One exception should be noted: When the locking bolt E^5 is rendered active after a centering operation or random quadding with the left-hand jaw, the jaw will not be adjusted with its stop because of their previous uncoupled condition. However, as soon as the left-hand jaw moves inwardly against its stop upon the inauguration of the casting cycle, the pawl E^{47} will drop into engagement with the lug C^{28} on the jaw automatically to effect their recoupling.

The mechanism for cutting out the light spring

G^{30} or G^{31} associated with the jaw which is active in quadding, that is, the lighter of the two springs through which the hydraulic clamping pressure is applied, comprises an interponent J^{28} which is moved into the path of one or another of the members G^{27} and G^{28} to which the springs G^{30} and G^{31} are connected and through which the force of the springs is applied to the bell crank levers G^{20} and G^{21} operating the respective plungers G^{16} and G^{17} (Figs. 3, 9 and 13). The interponent J^{28} is formed at the rear end of a bar J^{29} slidably mounted for movement in a fore-and-aft direction in lugs J^{30} fixed on the vise frame and which project upwardly from the fixed shelf B^3 . The members G^{27} and G^{28} are formed respectively with vertical arms G^{54} and G^{55} adapted to cooperate with the interponent. Normally, the interponent stands midway between the arms so as not to interfere with the rocking motion of the members in adding the effect of their springs G^{30} , G^{31} to that of the heavy springs G^{24} , G^{25} in applying the hydraulic pressure to the jaws when the machine is set for regular operation.

When the machine is set for quadding with the right-hand jaw, the bar J^{29} is moved rearwardly to locate the interponent J^{28} in the path of the arm G^{54} of the member G^{27} associated with the plunger G^{16} whose downward movement is instrumental in applying the clamping pressure to the right-hand jaw. The result is that when the cam D^5 , which times the application of the line clamping pressure, permits its associated lever G^{33} to release the bell crank levers G^{30} , G^{31} and the members G^{27} , G^{28} through which the spring reaction is applied, the interponent will block the movement of the member G^{27} associated with the right-hand jaw so that the line clamping pressure exerted by the right-hand jaw will result only from its heavy spring G^{24} . Under the circumstances, there will be a pressure differential in favor of the left-hand jaw, enabling it to remain firmly against its jaw stop despite the clamping pressure exerted by the right-hand jaw (Fig. 15).

On the other hand, when the machine is set for quadding left, the interponent J^{28} is moved from its central or normal position forwardly into the path of the arm G^{55} of the member G^{28} through which the reaction of the lighter spring G^{31} is applied to the plunger G^{17} associated with the left-hand jaw. During the quadding operation, the interponent will function to block the movement of the member G^{28} , the results being the same insofar as the left-hand jaw is concerned as they were for the right-hand jaw when the interponent was adjusted to its rearmost position.

During a centering operation, the interponent J^{28} is located in its normal central position clear of both the members G^{27} , G^{28} , since under such conditions there is no necessity for unbalancing the clamping pressure exerted upon the opposite ends of the line.

The interponent J^{28} is adjusted to its different positions automatically by the adjustment of the plate unit J^6 , J^7 . For this purpose, the fore-and-aft bar J^{29} is provided at its front end with a pin J^{31} which extends laterally through it and projects into a cam slot J^{32} formed in the right-hand plate J^6 , the bar being located just to the right of the plate unit as shown in Figs. 9 and 17. At the side opposite the plate J^6 , the bar J^{29} is flattened for a portion of its length to cooperate with a keeper plate J^{33} screwed to the fixed brack-

et J¹⁰ which serves as a guide for the plate unit, the keeper plate acting to prevent the bar J²⁹ from rotating and disturbing the proper relation of the interponent J²⁸ with the levers G²⁷ and G²⁸.

The configuration of the cam slot J³² and the relative positions of the pin J³¹ and the plate J⁶ for the different adjusted positions of the plate are shown in Fig. 19. The normal position of the pin J³¹, corresponding to the central or normal position of the interponent J²⁸, is shown at z². When the plate J⁶ is adjusted downwardly to the quadding right position, the pin J³¹, and consequently the bar J²⁹ with the interponent J²⁸ thereon, is cammed rearwardly to locate the interponent in its rearmost position. When the plate J⁶ is adjusted for a centering operation, the pin J³¹ is returned to its normal position wherein the interponent J²⁸ is again located between the members G²⁷ and G²⁸. And when the plate J⁶ is adjusted to the quadding left position, the pin J³¹ is cammed forwardly to locate the interponent J²⁸ in its foremost position. The relative positions of the pin J³¹ and plate J⁶ for such quadding right, centering and quadding left adjustments are shown at y², x² and w², respectively.

During a centering operation, the right and left-hand vise jaws C and C¹ are coupled together for equi-distant movement in opposite directions. The coupling mechanism is illustrated best in Figs. 2, 3, 9 and 21 and includes a clutch device consisting in part of two concentrically mounted gears J³⁴ and J³⁵. The lower gear J³⁴ is pinned to a sleeve J³⁶ rotatably mounted upon a vertical bearing post J³⁷, which latter is formed at its lower end with a flange screwed to the housing of the pneumatic mechanism which operates the left-hand jaw. The upper gear J³⁵ is pinned to another sleeve J³⁸ which encircles the sleeve J³⁶ and is rotatable relatively therewith. Above the sleeve J³⁸, there is located a third sleeve member J³⁹ likewise encircling the sleeve J³⁶ but which is constrained to rotate therewith by means of a pin J⁴⁰ threaded radially through an enlarged portion of the sleeve J³⁹ and projecting into a vertical slot J⁴¹ formed in said sleeve J³⁶. The upper sleeve J³⁹ is adjustable vertically to two different positions with respect to the sleeve J³⁶, the adjusted position being maintained by a spring detent J⁴² mounted in the enlarged portion of the sleeve J³⁹ and adapted to cooperate with one or another of a pair of vertically spaced notches J⁴³ formed in the sleeve J³⁶.

The lower gear J³⁴ (the one pinned to the inner sleeve J³⁶) meshes with a gear J⁴⁴ fast to the vertical shaft F³ which operates the left-hand jaw (Fig. 3); whereas the upper gear J³⁵ (the one pinned to the lower outer sleeve J³⁸) meshes with the teeth of a rack bar J⁴⁵ guided for horizontal movement in fixed lugs J⁴⁶ and which, at its right end, meshes with a gear J⁴⁷ pinned on the vertical shaft F which operates the right-hand jaw (Fig. 9). When the sleeve member J³⁹ is in its upper position of adjustment, the gears J³⁴ and J³⁵ will rotate independently, if at all, in accordance with the movement of the jaws to which they are respectively connected, the upper gear J³⁵ rotating in the same direction as the shaft F of the right-hand jaw because of its rack connection therewith, and the lower gear J³⁴ rotating in a direction opposite to that of the shaft F³ of the left-hand jaw because of its geared connection therewith.

When the machine is set for a centering operation, however, the upper sleeve member J³⁹ is moved to its lower position of adjustment, where-

in a toothed flange J⁴⁸ formed at its lower end engages a complementary toothed flange J⁴⁹ formed at the top of the lower sleeve member J³⁸. In other words, the sleeve members J³⁸ and J³⁹ are coupled together, causing the upper and the lower gear elements J³⁴ and J³⁵ to rotate as a unit. Under such conditions, the vertical shafts F and F³, operating the right and the left-hand jaws, will have the same degree of rotational movement although in opposite directions, with the result that the two jaws will move equal distances toward each other, that being the essential prerequisite for centering a composed line.

The adjustable sleeve J³⁹ of the clutch mechanism is moved to its different positions by the control plate unit J⁶, J⁷ through an intermediate composite bell crank member consisting of a vertical arm J⁵⁰, formed integral with a hub J⁵¹ journalled on a bearing rod J⁵² fixed in a vertical portion of the vise frame, and a relatively movable member J⁵³, likewise journalled on the bearing rod J⁵² and formed with a horizontal rearwardly extending arm J⁵⁴ engaging at its rear end between the enlarged upper portion of the sleeve member J³⁹ and the flange J⁴⁸ formed at the bottom thereof (Figs. 2, 3, and 21). A vertical depending arm J⁵⁵, likewise formed integral with the hub member J⁵¹, is provided at its lower end with a laterally extending lip J⁵⁶ arranged to engage the rear edge of the vertical arm J⁵⁰ first alluded to. The two arms J⁵⁰ and J⁵⁴ are resiliently held together by a tension spring J⁵⁷ connected, at its opposite ends, to pins J⁵⁸ provided one on each of said arms. The purpose of this two-arm arrangement is to permit the arms J⁵⁰ and J⁵⁴ to yield relatively during the engagement of the clutch members in the event there should be end to end contact between the teeth of the flanges J⁴⁸ and J⁴⁹ when the parts are moved together. Under such conditions, of course, a very slight relative movement between the clutch members will cause them to seat properly with their teeth interengaged, such relative movement being almost certain to occur when the quadding movement of the jaws is inaugurated.

The longer depending arm J⁵⁰ of the composite bell crank lever is formed at its lower end with a pin J⁵⁹ extending laterally to the right and engaging in a slot J⁶⁰ formed in the left-hand plate J⁷ of the adjustable plate control unit. The normal position of the pin with reference to the plate for regular machine operation is shown by the solid lines at z³ in Fig. 19, whereas its relative positions for the other plate adjustments are shown by the dot and dash lines at y³, x³ and w³. As will be observed, in every adjusted position of the plate J⁷ except for centering, the pin J⁵⁹ is located in its normal position to maintain the clutch in its disengaged condition. As the plate J⁷ is adjusted to the centering position, however, the pin J⁵⁹ is cammed forwardly to turn the composite bell crank lever in a direction to engage the clutch member and couple the jaws together.

One of the advantages of the instant device resides in the fact that it can also be used for offset centering with respect to the mold slot. By way of example, if the mold slot is of 30 ems length, the stop E¹ associated with the left-hand jaw may be set manually for an indentation at the left of 6 ems, i. e., to "24" on the em scale E¹, it being understood that at the time the setting is made the machine is set for regular operation. Under such conditions, the left-hand jaw will likewise be set in its fixed quadding position since,

at the time, it will be coupled for movement with its stop. Now when the machine is conditioned for centering by the adjustment of the disk J, the jaws will be coupled together, so that during the machine cycle the left-hand jaw will start its centering movement from the 24 em position on the scale, whereas the right-hand jaw will start its centering movement from its full line or extreme right-hand position. To obtain this effect, it is necessary that the cam slot J⁶⁰ in the plate J⁷ effect the jaw coupling movement of the pin J⁵⁹ prior to the movement of the pin J²⁴ in effecting the disabling of the pawl E⁴⁷ which normally couples the left-hand jaw C¹ to the stop E¹. As shown in Fig. 19, the configurations of the cam slot J⁶⁰ for the pin J⁵⁹ and the cam surface at the top of the plate J⁷ for the pin J²⁴ are such as to operate the two pins in the proper sequence.

The cam shaft and manifold

While the valves C¹¹, G⁵⁰, H⁷ and F²⁴ controlling the various pneumatic devices have been treated separately, actually they are all contained in the common manifold D³ which is mounted on the vise frame bracket B⁹ that also serves to support the pressure regulating valve J¹² (Figs. 1, 16 and 26). And while the valves are individually guided as they are adjusted from one position to another, they have a common high pressure chamber D¹⁷ in the manifold which is connected to a source of air pressure through a single pipe line D¹⁸. Of course, all of the pneumatic devices have individual pipe line connections with the manifold which are opened and closed by their respective valves as the operation of the machine dictates.

All of the swivel bell crank levers C¹⁷, G⁵², H⁹ and F²⁸ for operating the valves are arranged on the common fore-and-aft shaft B³ which is mounted at its ends in the bracket B⁹. Those bell crank levers that require spring tension to maintain them in edge contact with their operating cams (i. e., all of the levers with the exception of the lever C¹⁷ which controls the raising and lowering of the right-hand jaw slide) have individual springs D¹⁹ connected to them, the springs being anchored at their upper ends to a common overlying bar D²⁰ which likewise is supported at its ends in the bracket B⁹ (Figs. 1 and 16). The cam shaft D, which mounts the valve controlling cams, is disposed immediately adjacent the manifold, so that the control unit as a whole is compact and contains a minimum number of parts.

The cam shaft D is journalled at its opposite ends in fixed portions of the vise frame and is driven from the main cam shaft D²¹ of the machine through connections which permit the vise frame, which is pivotally mounted at the left, to be swung open when it becomes necessary to gain access to the parts (Fig. 3). The main cam shaft D²¹ drives a supplementary cam shaft D²² through a train including three gears D²³, D²⁴, D²⁵. The purpose of the shaft D²² is fully set forth in the Plastaras application Serial No. 377,364 to which repeated reference has been made. It is mentioned here merely because the cam shaft D in the vise frame is driven, not directly from the main cam shaft D²¹, but from the gear D²⁵ which is mounted on the lower supplementary cam shaft D²², the driving connections being such as to cause the cam shaft D to rotate at the same speed as the main cam shaft D²¹.

The means for driving the cam shaft D further

include a short fore-and-aft counter shaft D²⁶ provided at its rear end with a gear D²⁷ meshing with the gear D²⁵ and provided at its front end with a similar gear D²⁸ meshing with a gear D²⁹ rotatably mounted on a short bearing rod D³⁰ presented by a fixed part of the machine and located coaxially with the cam shaft D. The driving connection between the gear D²⁹ and the cam shaft D includes a pin D³¹ projecting forwardly from the gear and adapted when the vise frame is closed to engage in a notch presented by a circular plate D³² formed at the rear end of said cam shaft. As will now be apparent, the driving connection just described is readily broken as the vise frame is swung open and readily established when the vise frame is closed. Furthermore, since the closing of the vise frame requires registry between the pin D³¹ and the notch in the plate D³², the cam shaft D will always be located so as to time the operations controlled thereby in proper relation to the operations controlled from the main cam shaft D²¹.

While in each instance a definite timing has been set forth in connection with charging and venting the different pneumatic cylinder and piston devices, that timing may be revised, if necessary, to facilitate certain of the machine operation. For instance, according to the description, one cylinder of each vise jaw operating pair is charged to move its jaws inwardly while the other cylinder of the pair is vented, the conditions then being reversed to move the jaws outwardly. Under such operating conditions, there will be a modicum of pneumatically generated line clamping pressure effective throughout matrix alignment. Ordinarily, matrix alignment will suffer no interference, but if this pressure be found excessive, both cylinders of the pairs associated with the respective jaws may be vented during matrix alignment by suitably revising the air valve construction together with its operating cam. And in the case of the justification cylinder, the venting of the upper end thereof may be timed slightly to anticipate the charging of its lower end instead of effecting those operations simultaneously as has been described. Such a timing revision will speed up the justifying operation, thus giving more time for the performance of other machine operations.

Conclusion

It is believed that the operations of the various mechanisms have been sufficiently described under the different headings and that therefore any further effort in that direction would be superfluous.

In the accompanying drawings, the invention has been shown merely in preferred form and by way of example, but obviously many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. In a slug casting machine, the combination of a pair of line clamping jaws, at least one of which is movable from a normal full line receiving position to a quadding position and return, and pneumatic mechanism for effecting such quadding movement of the jaw.

2. In a slug casting machine, the combination of a pair of line clamping jaws, at least one of

which is movable from a normal full line receiving position to a quadding position and return, and pneumatic mechanism for effecting such quadding and return movements of the jaw.

3. A combination according to claim 1, including timing means for controlling the automatic operation of said pneumatic mechanism.

4. A combination according to claim 2, including timing means for controlling the automatic operation of said pneumatic mechanism.

5. In a slug casting machine, the combination of a pair of line clamping jaws, at least one of which is movable from a normal full line receiving position to a quadding position and return, pneumatic mechanism for effecting such quadding movement of the jaw, said pneumatic mechanism including a cylinder and piston device connected to the jaw, and an automatically operated valve controlling the charging and venting of the cylinder.

6. In a slug casting machine, the combination of a pair of line clamping jaws, at least one of which is movable from a normal full line receiving position to a quadding position and return, pneumatic mechanism for effecting such quadding and return movements of the jaw, said pneumatic mechanism including a pair of oppositely-acting cylinder and piston devices connected to the jaw, and an automatically operated valve controlling the charging and venting of the two cylinders in proper alternation.

7. A combination according to claim 5, wherein the connections between the jaw and the pneumatic cylinder and piston device comprise a rotary shaft provided with two pinions, one meshing with a rack carried by the jaw, and the other with a rack carried by the piston.

8. A combination according to claim 6, wherein the connections between the jaws and the pneumatic cylinder and piston devices comprise a rotary shaft provided with two pinions, one meshing with a rack carried by the jaw, and the other with the racks carried by the pistons.

9. In a slug casting machine, the combination of a pair of line clamping jaws, at least one of which is movable from a normal full line receiving position to a quadding position and return, and hydraulic mechanism operative during casting to hold the jaw against retreat from its quadding position and operative after casting to release said jaw for return movement.

10. In a slug casting machine, the combination of a pair of line clamping jaws, at least one of which is movable from a normal full line receiving position to a quadding position and return, and hydraulic mechanism operative during casting to exert an inward clamping pressure on the jaw while in quadding position and operative after casting to release said jaw for return movement.

11. A combination according to claim 9, including timing means for controlling the operation of said hydraulic mechanism.

12. A combination according to claim 10, including timing means for controlling the operation of said hydraulic mechanism.

13. In a slug casting machine, the combination of a pair of line clamping jaws, at least one of which is movable from a normal full line receiving position to a quadding position and return, hydraulic mechanism operative during casting to hold the jaw against retreat from its quadding position and operative after casting to release said jaw for return movement, said hydraulic mechanism including a cylinder and piston device connected to the jaw, a liquid reservoir in com-

munication with the cylinder, and an automatically operated valve to shut off and to reestablish such communication before and after casting, respectively.

14. In a slug casting machine, the combination of a pair of line clamping jaws, at least one of which is movable from a normal full line receiving position to a quadding position and return, hydraulic mechanism operative during casting to exert an inward clamping pressure on the jaw while in quadding position and operative after casting to release said jaw for return movement, said hydraulic mechanism including a cylinder and piston device connected to the jaw, a liquid reservoir in communication with the cylinder, and an automatically operated valve plunger to shut off communication and build up pressure on the piston before casting and to reestablish such communication after casting.

15. A combination according to claim 14, wherein the automatic operation of the valve plunger is controlled by a cam acting in opposition to a spring which effects the pressure stroke of the plunger.

16. A combination according to claim 14, wherein the automatic operation of the valve plunger is controlled by a cam acting in opposition to a spring which effects the pressure stroke of the plunger and including power means to aid the cam in overcoming the force of the spring in effecting the return stroke of the valve plunger.

17. A combination according to claim 14, wherein the automatic operation of the valve plunger is controlled by a cam acting in opposition to a spring which effects the pressure stroke of the plunger and including pneumatic means to aid the cam in overcoming the force of the spring in effecting the return stroke of the valve plunger.

18. A combination according to claim 14, wherein the automatic operation of the valve plunger is controlled by a cam acting in opposition to a spring which effects the pressure stroke of the plunger and including a pneumatic cylinder and piston device to aid the cam in overcoming the force of the spring in effecting the return stroke of the valve plunger, and an automatically operated valve controlling the charging and venting of the cylinder.

19. A combination according to claim 13, wherein the connection between the jaw and the hydraulic cylinder and piston device comprises a rotary shaft provided with two pinions, one meshing with a rack carried by the jaw, and the other with a rack carried by the piston.

20. A combination according to claim 14, wherein the connection between the jaw and the hydraulic cylinder and piston device comprises a rotary shaft provided with two pinions, one meshing with a rack carried by the jaw, and the other with a rack carried by the piston.

21. In a slug casting machine, the combination of a pair of line clamping jaws, at least one of which is movable from a normal full line receiving position to a quadding position and return, pneumatic mechanism for effecting such quadding movement of the jaw, and hydraulic mechanism operative during casting to hold the jaw against retreat from its quadding position and operative after casting to release said jaw for return movement.

22. In a slug casting machine, the combination of a pair of line clamping jaws, at least one of which is movable from a normal full line re-

ceiving position to a quadding position and return, pneumatic mechanism for effecting such quadding movement of the jaw, and hydraulic mechanism operative during casting to exert an inward clamping pressure on the jaw while in quadding position and operative after casting to release said jaw for return movement.

23. A combination according to claim 21, including timing means for controlling the automatic operation of said pneumatic and hydraulic mechanisms in proper sequence.

24. A combination according to claim 22, including timing means for controlling the automatic operation of said pneumatic and hydraulic mechanisms in proper sequence.

25. In a slug casting machine, the combination of a pair of line clamping jaws, at least one of which is movable from a normal full line receiving position to a quadding position and return, pneumatic mechanism for effecting such quadding movement of the jaw, said pneumatic mechanism including a cylinder and piston device connected to the jaw, and an automatically operated valve controlling the charging and venting of the cylinder, hydraulic mechanism operative during casting to hold the jaw against retreat from its quadding position and operative after casting to release said jaw for return movement, said hydraulic mechanism including a cylinder and piston device connected to the jaw, a liquid reservoir in communication with the cylinder, and an automatically operated valve to shut off and reestablish such communication before and after casting, characterized in that the connection between the jaw and the pneumatic cylinder and piston device as well as the connection between the jaw and the hydraulic cylinder and piston device comprise a rotary shaft provided with three pinions, one meshing with a rack carried by the jaw, a second meshing with racks carried by the pneumatic piston, and a third meshing with a rack carried by the hydraulic piston.

26. In a slug casting machine, the combination of a pair of line clamping jaws, at least one of which is movable from a normal full line receiving position to a quadding position and return, pneumatic mechanism for effecting such quadding movement of the jaw, said pneumatic mechanism including a cylinder and piston device connected to the jaw, and an automatically operated valve controlling the charging and venting of the cylinder, hydraulic mechanism operative during casting to exert an inward clamping pressure on the jaw while in quadding position and operative after casting to release said jaw for return movement, said hydraulic mechanism including a cylinder and piston device connected to the jaw, a liquid reservoir in communication with the cylinder, and an automatically operated valve plunger to shut off communication and build up pressure on the piston before casting and to reestablish such communication after casting, characterized in that the connection between the jaw and the pneumatic cylinder and piston device as well as the connection between the jaw and the hydraulic cylinder and piston device comprise a rotary shaft provided with three pinions, one meshing with a rack carried by the jaw, a second with a rack carried by the pneumatic piston, and a third meshing with a rack carried by the hydraulic piston.

27. In a slug casting machine, the combination of a pair of line clamping jaws, at least one of which is movable from a normal full line receiving position to a quadding position and return,

pneumatic mechanism for effecting such quadding and return movements of the jaw, said pneumatic mechanism including a pair of oppositely-acting cylinder and piston devices connected to the jaw, and an automatically operated valve controlling the charging and venting of the two cylinders in proper alternation, hydraulic mechanism operative during casting to hold the jaw against retreat from its quadding position and operative after casting to release said jaw for return movement, said hydraulic mechanism including a cylinder and piston device connected to the jaw, a liquid reservoir in communication with the cylinder and an automatically operated valve to shut off and to reestablish such communication before and after casting, respectively, characterized in that the connection between the jaw and the pneumatic cylinder and piston devices as well as the connection between the jaw and the hydraulic cylinder and piston device comprise a rotary shaft provided with three pinions, one meshing with a rack carried by the jaw, a second meshing with racks carried by the pneumatic piston, and a third meshing with a rack carried by the hydraulic piston.

28. In a slug casting machine, the combination of a pair of line clamping jaws, at least one of which is movable from a normal full line receiving position to a quadding position and return, pneumatic mechanism for effecting such quadding and return movements of the jaw, said pneumatic mechanism including a pair of oppositely-acting cylinder and piston devices connected to the jaw, and an automatically operated valve controlling the charge and venting of the two cylinders in proper alternation, hydraulic mechanism operative during casting to exert an inward clamping pressure on the jaw while in quadding position and operative after casting to release said jaw for return movement, said hydraulic mechanism including a cylinder and piston device connected to the jaw, a liquid reservoir in communication with the cylinder, and an automatically operated valve plunger to shut off communication and build up pressure on the piston before casting and to reestablish such communication after casting, characterized in that the connection between the jaw and the pneumatic cylinder and piston devices as well as the connection between the jaw and the hydraulic cylinder and piston device comprise a rotary shaft provided with three pinions, one meshing with a rack carried by the jaw, a second with racks carried by the pneumatic piston, and a third meshing with a rack carried by the hydraulic piston.

29. A combination according to claim 9, wherein the hydraulic mechanism is also operative before casting to release the jaw momentarily while in quadding position to facilitate the matrix alignment operation.

30. A combination according to claim 10, wherein the hydraulic mechanism is also operative before casting to release the jaw momentarily while in quadding position to facilitate the matrix alignment operation.

31. A combination according to claim 21, wherein the hydraulic mechanism is also operative before casting to release the jaw momentarily while in quadding position to facilitate the matrix alignment operation.

32. A combination according to claim 22, wherein the hydraulic mechanism is also operative before casting to release the jaw momentar-

ily while in quadding position to facilitate the matrix alignment operation.

33. A combination according to claim 9, wherein the hydraulic pressure is gradually relieved before the jaw is completely released.

34. A combination according to claim 10, wherein the hydraulic pressure is gradually relieved before the jaw is completely released.

35. A combination according to claim 21, wherein the hydraulic pressure is gradually relieved before the jaw is completely released.

36. A combination according to claim 22, wherein the hydraulic pressure is gradually relieved before the jaw is completely released.

37. In a slug casting machine, the combination of a pair of line clamping jaws, at least one of which is movable from a normal full line receiving position to a quadding position and return, hydraulic mechanism operative after the jaw has reached its quadding position to hold the jaw against retreat therefrom during casting, and operative after casting to release said jaw for return movement, said hydraulic mechanism being also operative before casting to release the jaw momentarily while in quadding position to facilitate the matrix alignment operation, and means for gradually relieving the hydraulic pressure on the jaw before the jaw is completely released.

38. In a slug casting machine, the combination of a pair of line clamping jaws, at least one of which is movable from a normal full line receiving position to a quadding position and return, hydraulic mechanism operative after the jaw has reached its quadding position to exert an inward clamping pressure on the jaw and operative after casting to release said jaw for return movement, said hydraulic mechanism being also operative after the clamping pressure has been initially applied but before casting to release the jaw momentarily while in quadding position to facilitate the matrix alignment operation, and means for gradually relieving the hydraulic pressure on the jaw before the jaw is completely released.

39. In a slug casting machine, the combination of a pair of line clamping jaws, at least one of which is movable from a normal full line receiving position to a quadding position and return, pneumatic mechanism for effecting such quadding movement of the jaw, hydraulic mechanism operative after the jaw has reached its quadding position to hold the jaw against retreat therefrom during casting and operative after casting to release said jaw for return movement, said hydraulic mechanism being also operative before casting to release the jaw momentarily while in quadding position to facilitate the matrix alignment operation, and means for gradually relieving the hydraulic pressure on the jaw before the jaw is completely released.

40. In a slug casting machine, the combination of a pair of line clamping jaws, at least one of which is movable from a normal full line receiving position to a quadding position and return, pneumatic mechanism for effecting such quadding movement of the jaw, hydraulic mechanism operative after the jaw has reached its quadding position to exert an inward clamping pressure on the jaw and operative after casting to release said jaw for return movement, said hydraulic mechanism being also operative after the clamping pressure has been initially applied but before casting to release the jaw momentarily while in quadding position to facilitate the matrix alignment operation, and means for gradually relieving the hydraulic pressure on the jaw before the jaw is completely released.

alignment operation, and means for gradually relieving the hydraulic pressure on the jaw before the jaw is completely released.

41. In a slug casting machine, the combination of a pair of line clamping jaws each movable inwardly from a normal full line receiving position to a quadding position and return, a stop for each of said jaws and adapted when active to limit its inward movement, and machine conditioning means for preventing the quadding movement of one jaw while permitting the quadding movement of the other jaw, or for preventing the quadding movement of either jaw, or for permitting the quadding movement of both jaws, as desired, said conditioning means acting to render the stops inactive or active according as the quadding movement of the respective jaw is permitted or prevented.

42. A combination according to claim 9, wherein the hydraulic pressure exerted on the jaw may be increased or diminished as required.

43. A combination according to claim 10, wherein the hydraulic pressure exerted on the jaw may be increased or diminished as required.

44. A combination according to claim 1, wherein the full line receiving position of the jaw is determined by a stop which prevents the inward movement of the jaw beyond that position.

45. A combination according to claim 9, wherein the full line receiving position of the jaw is determined by a stop which prevents the inward movement of the jaw beyond that position.

46. A combination according to claim 21, wherein the full line receiving position of the jaw is determined by a stop which prevents the inward movement of the jaw beyond that position.

47. In a slug casting machine, the combination of a pair of line clamping jaws, at least one of which is movable from a normal full line receiving position to a quadding position and return, hydraulic mechanism operative during casting to hold the jaw against retreat from its quadding position and operative before casting to release the jaw momentarily while in quadding position to facilitate the matrix alignment operation and operative after casting to release said jaw for return movement, the full line receiving position of the jaw being determined by a stop which prevents the inward movement of the jaw beyond that position.

48. A combination according to claim 1, wherein the quadding position of the jaw for fixed indentation is predetermined by a stop which prevents the inward movement of the jaw beyond that predetermined position.

49. A combination according to claim 9, wherein the quadding position of the jaw for fixed indentation is predetermined by a stop which prevents the inward movement of the jaw beyond that predetermined position.

50. A combination according to claim 21, wherein the quadding position of the jaw for fixed indentation is predetermined by a stop which prevents the inward movement of the jaw beyond that predetermined position.

51. In a slug casting machine, the combination of a pair of line clamping jaws, at least one of which is movable from a normal full line receiving position to a quadding position and return, hydraulic mechanism operative during casting to hold the jaw against retreat from its quadding position and operative before casting to release the jaw momentarily while in quadding position to facilitate the matrix alignment operation.

operation, the quadding position of the jaw for fixed indentation being predetermined by a stop which prevents the inward movement of the jaw beyond that predetermined position.

52. A combination according to claim 1, wherein the normal full line receiving position or the quadding position of the jaw is determined by an adjustable stop which is settable to prevent the inward movement of the jaw beyond one position or the other, as desired.

53. A combination according to claim 9, wherein the normal full line receiving position or the quadding position of the jaw is determined by an adjustable stop which is settable to prevent the inward movement of the jaw beyond one position or the other, as desired.

54. A combination according to claim 21, wherein the normal full line receiving position or the quadding position of the jaw is determined by an adjustable stop which is settable to prevent the inward movement of the jaw beyond one position or the other, as desired.

55. In a slug casting machine, the combination of a pair of line clamping jaws, at least one of which is movable from a normal full line receiving position to a quadding position and return, hydraulic mechanism operative during casting to hold the jaw against retreat from its quadding position and operative before casting to release the jaw momentarily while in quadding position to facilitate the matrix alignment operation, the normal full line receiving position or the quadding position of the jaw being determined by an adjustable stop which is settable to prevent the inward movement of the jaw beyond one position or the other, as desired.

56. In a slug casting machine, the combination of a pair of line clamping jaws, at least one of which is movable from a normal full line receiving position to a quadding position and return, pneumatic mechanism for effecting such quadding movement of the jaw, a stop for determining the full line receiving position of the jaw and which is adapted when operative to prevent the inward movement of the jaw beyond that position, and means for rendering the stop inactive to permit the quadding position of the jaw to be determined by direct contact of the jaw with the composed line in the jaw's inward movement for free or random quadding.

57. In a slug casting machine, the combination of a pair of line clamping jaws, at least one of which is movable from a normal full line receiving position to a quadding position and return, pneumatic mechanism for effecting such quadding movement of the jaw, a stop adjustable to predetermine the quadding position of the jaw for fixed indentation and which is adapted when operative to prevent the inward movement of the jaw beyond that predetermined position, and means for rendering the stop inactive to permit the quadding position of the jaw to be determined by direct contact of the jaw with the composed line in the jaw's inward movement for free or random quadding.

58. In a slug casting machine, the combination of a pair of line clamping jaws, at least one of which is movable from a normal full line receiving position to a quadding position and return, pneumatic mechanism for effecting such quadding movement of the jaw, an adjustable stop for determining the normal full line receiving position or the quadding position of the jaw and which is settable to prevent the inward movement of the jaw beyond one position or an-

other, as desired, and means for adjusting the jaw stop to and locking it in any of its adjusted positions, said means comprising a rotary shaft connected by a rack and pinion to the jaw stop, said rack having locking teeth formed therein and a toothed locking bolt movable into and out of engagement with said rack locking teeth to permit the adjustment of the jaw stop.

59. In a slug casting machine, the combination of a pair of line clamping jaws, at least one of which is movable from a normal full line receiving position to a quadding position and return, pneumatic mechanism for effecting such quadding movement of the jaw, an adjustable stop for determining the normal full line receiving position or the quadding position of the jaw and which is settable to prevent the inward movement of the jaw beyond one position or another, as desired, and means for adjusting the jaw stop to and locking it in any of its adjusted positions, said means comprising a rotary shaft connected by a rack and pinion to the jaw stop and shiftable axially without breaking said rack and pinion connection, locking teeth formed in said rack, a toothed locking bolt movable into and out of engagement with said rack locking teeth to permit the adjustment of the jaw stop, and coupling means for permitting said movements of the toothed locking bolt by said axial movement of the adjusting shaft.

60. A combination according to claim 59, wherein the toothed locking bolt is normally engaged with the locking teeth of the jaw stop rack, and including means independent of the adjusting shaft for disengaging the locking bolt to permit a free or random quadding movement of the jaw.

61. A combination according to claim 59, wherein the left-hand jaw is the quadding jaw and wherein the toothed locking bolt is normally engaged with the locking teeth of the jaw stop rack, and including means acting normally to couple said jaw to the stop for simultaneous adjustment therewith, and means independent of the adjusting shaft for disengaging the locking bolt and concurrently disabling the jaw coupling means to permit a free or random quadding movement of the jaw.

62. A combination according to claim 59, including an indicating scale mounted on the fixed vise frame, and a pointer co-operating with the scale and carried by a rack separate and distinct from the jaw stop rack, and wherein the two said racks are operated in unison by the pinion on the rotary adjusting shaft.

63. A combination according to claim 58, wherein the locking teeth on the jaw stop rack are spaced for coarse adjustments of the jaw stop, and including means for adjusting the locking bolt bodily in a lateral direction after its engagement with said rack locking teeth for finer adjustments of the jaw stop.

64. In a slug casting machine, the combination of left hand and right hand line clamping jaws, the right hand jaw being movable from a normal full line receiving position to a quadding position and return, and normally standing out of operative relation to the left hand jaw, and means for moving said right hand jaw into operative relation with the left hand jaw before its quadding movement is effected.

65. In a slug casting machine, the combination of left and right hand line clamping jaws, the right hand jaw normally standing out of operative relation to the left hand jaw and

adapted when located in operative relation therewith to be moved from a normal full line receiving position to a quadding position and return, and means including a shaft provided with a pinion meshing with a rack carried by the right hand jaw and rotatable to effect the quadding and return movement thereof, said pinion being splined to the shaft to permit the jaw to be moved vertically into and out of operative relation to the left hand jaw at the proper time.

66. In a slug casting machine, the combination of left and right hand line clamping jaws, the right hand jaw normally standing out of operative relation to the left hand jaw and adapted when located in operative relation therewith to be moved from a normal full line receiving position to a quadding position and return, pneumatic mechanism including cylinder and piston means connected to the right hand jaw, and an automatically operated valve controlling the charging and venting of the cylinder means thereof, said jaw connection comprising a rotary shaft provided with two pinions, one meshing with a rack carried by the jaw and the other with rack means carried by the piston means, the pinion on the rotary shaft meshing with the jaw rack being splined to said shaft to permit the jaw to be moved vertically into and out of operative relation to the left hand jaw at the proper time.

67. In a slug casting machine, the combination of left hand and right hand line clamping jaws, the right hand jaw normally standing out of operative relation to the left hand jaw and adapted when located in operative relation therewith to be moved from a normal full line receiving position to a quadding position and return, hydraulic mechanism operative during casting to hold the jaw against retreat from its quadding position and operative after casting to release said jaw for return movement, said hydraulic mechanism including a cylinder and piston device connected to the jaw, a liquid reservoir in communication with the cylinder, and an automatically operated valve to shut off and to reestablish such communication before and after casting, respectively, said jaw connection comprising a rotary shaft provided with two pinions, one meshing with a rack carried by the jaw and the other with a rack carried by the piston, the pinion on the rotary shaft meshing with the jaw rack being splined to said shaft to permit the jaw to be moved vertically into and out of operative relation to the left hand jaw at the proper time.

68. In a slug casting machine, the combination of left hand and right hand line clamping jaws, the right hand jaw normally standing out of operative relation to the left hand jaw and adapted when located in operative relation therewith to be moved from a normal full line receiving position to a quadding position and return, pneumatic mechanism including a cylinder and piston means connected to the right hand jaw, an automatically operated valve controlling the charging and venting of the cylinder means, hydraulic mechanism operative during casting to hold the jaw against retreat from its quadding position and operative after casting to release said jaw for return movement, said hydraulic mechanism including a cylinder and piston device connected to the jaw, a liquid reservoir in communication with the cylinder, and an automatically operated valve to shut off and reestablish such communication before and after casting, respectively, said connection between the jaw and the pneumatic cylinder and piston means

as well as the connection between the jaw and the hydraulic cylinder and piston device comprising a rotary shaft provided with three pinions, one meshing with a rack carried by the jaw, a second with rack means carried by the pneumatic piston means, and a third meshing with a rack carried by the hydraulic piston, the pinion on the rotary shaft meshing with the jaw rack being splined to said shaft to permit the jaw to be moved vertically into and out of operative relation to the left hand jaw at the proper time.

69. In a slug casting machine equipped with a pair of line clamping jaws, the left-hand jaw being movable automatically from a normal full line receiving position to a quadding position and return, the combination of an adjustable stop to locate said left-hand jaw in one position or the other, as desired, said stop being adapted to be rendered inactive to permit a free or random quadding movement of the jaw, and means for coupling the said jaw to the stop for simultaneous adjustment therewith when the stop is active.

70. A combination according to claim 69, including means for temporarily disabling the coupling means when the jaw stop is rendered inactive for a free or random quadding movement of the jaw.

71. In a slug casting machine, the combination of a pair of line clamping jaws movable each from a normal full line receiving position to a quadding position and return, a stop associated with each jaw for determining the full line receiving position thereof by preventing the inward movement of the jaw beyond that position, and machine conditioning means, common to both of the jaw stops, for rendering either one or both inactive as desired.

72. In a slug casting machine, the combination of a pair of line clamping jaws movable each from a normal full line receiving position to a quadding position and return, an adjustable stop associated with each jaw and which is settable to predetermine the quadding position of the jaw for fixed indentation and which acts to prevent the inward movement of the jaw beyond that predetermined position, and machine conditioning means, common to both of the jaw stops, for rendering either one or both inactive as desired.

73. In a slug casting machine, the combination of a pair of line clamping jaws movable each from a normal full line receiving position to a quadding position and return, an adjustable stop associated with each jaw for determining its normal full line receiving position or its quadding position and which is settable to prevent the inward movement of the jaw beyond one position or the other as desired, and machine conditioning means, common to both of the jaw stops, for rendering either one or both inactive as desired.

74. A combination according to claim 58, wherein each of the line clamping jaws is the quadding jaw, and including machine conditioning means, common to both of the jaw stop locking bolts and independent of their respective adjusting shafts, for disengaging either one or both of said bolts, as required.

75. A combination according to claim 59, wherein each of the line clamping jaws is the quadding jaw, and including machine conditioning means, common to both of the jaw stop locking bolts and independent of their respective adjusting shafts, for disengaging either one or both of said bolts, as required.

76. A combination according to claim 58, wherein each of the line clamping jaws is the quadding jaw and including means acting normally to couple the left hand jaw to its stop for simultaneous adjustment therewith, and machine conditioning means, common to both of the jaw stop locking bolts and independent of their respective adjusting shafts, for disengaging either one or both of said bolts, as required, and for disengaging said coupling means whenever the left hand jaw stop locking bolt is disengaged.

77. In a slug casting machine, the combination of a pair of line clamping jaws, movable each from a normal full line receiving position to a quadding position and return, an adjustable stop associated with each jaw and which is settable to prevent the inward movement of the jaw beyond a predetermined position, machine conditioning means, common to both of the jaw stops, for selectively rendering either one or both stops inactive as desired to permit random quadding with either jaw or centering, hydraulic devices operative during casting to hold the jaws against their respective stops when active or to apply a clamping pressure on either jaw while in quadding position should its respective stop be inactive, and means for equalizing the hydraulic pressure exerted on the two jaws when their respective stops are both rendered either active or inactive and for creating a differential pressure in favor of the jaw whose stop remains active when the stop for the other jaw is rendered inactive.

78. A combination according to claim 77, wherein the means for equalizing the hydraulic pressure upon the jaws or creating the differential pressure, as the case may be, is controlled by the machine conditioning means.

79. A combination according to claim 77, wherein said hydraulic control devices include a hydraulic mechanism for each jaw and a pair of springs for each hydraulic mechanism, and means to permit the operation of both pairs of springs for an equalized pressure on the two jaws or to suppress one of the springs of either pair for a differential pressure on said jaws.

80. A combination according to claim 1, wherein each of the line clamping jaws is the quadding jaw, and including machine conditioning means for preventing the quadding movement of one jaw while permitting the quadding movement of the other jaw, or for preventing the quadding movement of either jaw, or for permitting the quadding movement of both jaws, as desired.

81. A combination according to claim 9, wherein each of the line clamping jaws is the quadding jaw, and including machine conditioning means for preventing the quadding movement of one jaw while permitting the quadding movement of the other jaw, or for preventing the quadding movement of either jaw, or for permitting the quadding movement of both jaws, as desired.

82. A combination according to claim 71, wherein the machine conditioning means include devices for coupling the two jaws together for simultaneous operation when both jaw stops are rendered inactive.

83. A combination according to claim 72, wherein the machine conditioning means include devices for coupling the two jaws together for simultaneous operation when both jaw stops are rendered inactive.

84. A combination according to claim 73, wherein the machine conditioning means include

devices for coupling the two jaws together for simultaneous operation when both jaw stops are rendered inactive.

85. In a slug casting machine, the combination of a pair of line clamping jaws, each of which is movable from a normal full line receiving position to a quadding position and return, pneumatic mechanism for effecting such quadding movements of the jaw, said pneumatic mechanism including cylinder and piston devices connected to each jaw, an automatically operated valve mechanism controlling the charging and venting of the cylinders, the connections between the jaws and their respective cylinder and piston devices comprising a rotary shaft provided with two pinions, one meshing with a rack carried by the jaw and the other with rack means associated with the cylinder and piston devices, and machine conditioning means for coupling together the rotary shafts connected to the respective jaws to insure equi-distant movement of both jaws when centering.

86. In a slug casting machine, the combination of a pair of line clamping jaws, each of which is movable from a normal full line receiving position to a quadding position and return, hydraulic mechanism associated with each jaw and operative during casting to exert an inward clamping pressure on the jaw while in casting position and operative after casting to release said jaw for return movement, connections between said hydraulic mechanisms and their respective jaws comprising a rotary shaft provided with two pinions, one meshing with a rack carried by the jaw and the other with a rack operated by the hydraulic mechanism, and machine conditioning means for coupling together the rotary shafts connected to the respective jaws to insure equi-distant movement of both jaws when centering.

87. In a slug casting machine, the combination of a pair of line clamping jaws, each of which is movable from a normal full line receiving position to a quadding position and return, pneumatic mechanism for effecting such quadding movements of the jaw, said pneumatic mechanism including cylinder and piston devices connected to each jaw, an automatically operated valve mechanism controlling the charging and venting of the cylinders, the connections between the jaws and their respective cylinder and piston devices comprising a rotary shaft provided with two pinions, one meshing with a rack carried by the jaw and the other with rack means associated with the cylinder and piston devices, machine conditioning means for coupling together the rotary shafts connected to the respective jaws to insure equi-distant movement of both jaws when centering, said coupling means including a clutch, and means for engaging and disengaging said clutch as desired.

88. In a slug casting machine, the combination of a pair of line clamping jaws, each of which is movable from a normal full line receiving position to a quadding position and return, hydraulic mechanism associated with each jaw and operative during casting to exert an inward clamping pressure on the jaw while in casting position and operative after casting to release said jaw for return movement, connections between said hydraulic mechanisms and their respective jaws comprising a rotary shaft provided with two pinions, one meshing with a rack carried by the jaw and the other with a rack operated by the hydraulic mechanism, machine

conditioning means for coupling together the rotary shaft connected to the respective jaws to insure equi-distant movement of both jaws when centering, said coupling means including a clutch, and means for engaging and disengaging said clutch as desired.

89. A combination according to claim 77, wherein the machine conditioning means comprise a single control member adjustable to four different positions to condition the machine for regular machine operation, quadding right, centering, or quadding left, as desired.

90. A combination according to claim 1, wherein each of the line clamping jaws is the quadding jaw and including machine conditioning means comprising a single control member adjustable to four different positions to condition the machine for regular machine operation, quadding right, centering, or quadding left, as desired, and means operative when the control member is thus adjusted, respectively, to prevent the quadding movement of either jaw, to prevent the quadding of the left hand jaw while permitting the quadding movement of the right, to permit the quadding movement of both jaws and to prevent the quadding movement of the right hand jaw while permitting the quadding movement of the left.

91. In a slug casting machine, the combination of a pair of line clamping jaws, movable each from a normal full line receiving position to a quadding position and return, means for predetermining the casting position of either jaw for normal machine operation or fixed quadding, hydraulic mechanism operative during casting to hold either jaw against retreat when its casting position is predetermined or to exert an inward clamping pressure on the jaws while in a quadding position resulting from free or random quadding, and machine conditioning means comprising a single control member adjustable to four different positions to condition the machine for regular machine operation, quadding right, centering, or quadding left as desired, and means operative when the control means is thus adjusted respectively, to cause the hydraulic mechanism to act during casting to hold both jaws against retreat, to hold the left hand jaw against retreat while exerting a clamping pressure upon the right hand jaw, to exert a clamping pressure upon both jaws and to hold the right hand jaw against retreat while exerting a clamping pressure upon the left hand jaw.

92. A combination according to claim 91, wherein a normally operative stop is provided for each jaw and which is adjustable to predetermine its casting position for normal machine operation or fixed quadding and wherein the machine conditioning means includes devices for maintaining both stops operative, for maintaining the left hand stop operative while rendering the right hand stop inoperative, for rendering both stops inoperative and for rendering the left hand stop inoperative while maintaining the right hand stop operative according as the control member is adjusted to condition the machine for regular machine operation, right hand quadding, centering or left hand quadding.

93. A combination according to claim 91, wherein the machine conditioning means includes a device for coupling the jaws for equi-distant movement and which is rendered operable automatically when the control member is adjusted to condition the machine for centering.

94. A combination according to claim 91,

wherein the machine conditioning means includes devices operable to permit an equalization of the hydraulic pressure upon the jaws when the control member is adjusted for normal machine operation or for centering, and to create a differential pressure in favor of one jaw when the control member is adjusted for quadding with the other jaw.

95. In a slug casting machine wherein a composed line of matrices and spacebands is positioned between a pair of line clamping jaws for justification, the combination of a spaceband driver movable from a normal position of rest to expand the line between the jaws and return, valve controlled pneumatic mechanism for effecting such line expanding movement of the spaceband driver and means functioning during the machine cycle of operation for controlling the operation of the valve.

96. In a slug casting machine wherein a composed line of matrices and spacebands is positioned between a pair of line clamping jaws for justification, the combination of a spaceband driver movable from a normal position of rest to expand the line between the jaws and return, valve controlled pneumatic mechanism for effecting such line expanding and return movements of the spaceband driver and means functioning during the machine cycle of operation for controlling the operation of the valve.

97. In a slug casting machine wherein a composed line of matrices and spacebands is positioned between a pair of line clamping jaws for justification, the combination of a spaceband driver movable from a normal position of rest to expand the line between the jaws and return, pneumatic mechanism for effecting such line expanding movement of the spaceband driver, said pneumatic mechanism including a cylinder and piston device connected to the spaceband driver, and a valve automatically operated during the regular machine cycle for controlling the charging and venting of the cylinder.

98. In a slug casting machine wherein a composed line of matrices and spacebands is positioned between a pair of line clamping jaws for justification, the combination of a spaceband driver movable from a normal position of rest to expand the line between the jaws and return, pneumatic mechanism for effecting such line expanding and return movements of the spaceband driver, said pneumatic mechanism including a double-acting cylinder and piston device connected to the spaceband driver, and an automatically operated valve for charging first one end and then the other of the cylinder while simultaneously venting the opposite end thereof.

99. In a slug casting machine, wherein a composed line of matrices and spacebands is positioned between a pair of line clamping jaws for justification, the combination of a spaceband driver movable from a normal position of rest to expand the line between the jaws and return, valve controlled pneumatic mechanism for effecting such line expanding movement of the spaceband driver in two stages, at a reduced pressure in the first stage and at full pressure in the second stage, and means functioning during the machine cycle of operation for controlling the operation of the valve.

100. A combination according to claim 99, wherein the pneumatic pressure is relieved between the two stages to facilitate the matrix alignment operation.

101. A combination according to claim 99,

wherein the pneumatic pressure in the two justifying stages is controlled by an automatic pressure regulator.

102. A combination according to claim 99, wherein the pneumatic pressure in the two justifying stages is controlled by an automatic pressure regulator adjustable to vary the pneumatic pressure exerted on the spaceband driver in the two stages.

103. A combination according to claim 97, including a cut-off valve arranged in the pipe line leading to that end of the cylinder which is charged for the effective stroke of the spaceband driver, a pressure diaphragm to close said valve, two springs to resist the valve closing movement of the pressure diaphragm, and a cam controlled device to subject the pressure diaphragm to the influence of one spring during the first justifying stage and to the influence of both springs during the second justifying stage.

104. In a slug casting machine wherein a composed line of matrices and spacebands is justified between a pair of line clamping jaws, the combination of a spaceband driver movable in two stages to expand the line between the jaws, and means for effecting such line expanding movement of the spaceband driver, said means acting to apply a predetermined and relatively light force to the driver in the first stage and a predetermined and relatively heavy force thereto in the second stage.

105. In a slug casting machine, the combination of a pair of line clamping jaws, each of which is movable from a normal full line receiving position to a quadding position and return, and two separate and distinct mechanisms for effecting such quadding movements of the respective jaws.

106. A combination according to claim 105, including machine conditioning means for rendering one of said mechanisms effective and the other ineffective, as desired.

107. A combination according to claim 105, including machine conditioning means for rendering both of said mechanisms simultaneously effective or ineffective, as desired.

108. A combination according to claim 105, including machine conditioning means for coupling the two said mechanisms together for simultaneous operation when centering.

109. In a slug casting machine, the combination of a pair of line clamping jaws, each of which is movable automatically from a normal full line receiving position to a quadding position and return, and two separate and distinct mechanisms operative during casting to exert an inward clamping pressure on the respective jaws whether in full line receiving position or in quadding position.

110. A combination according to claim 109, including machine conditioning means for preventing the quadding movement of one jaw while permitting the quadding movement of the other jaw, and for effecting a relative adjustment of the two pressure exerting mechanisms whereby to create a differential clamping pressure in favor of the jaw denied the quadding movement.

111. A combination according to claim 109, including automatic means operative before casting for relieving the clamping pressure exerted on the respective jaws by the two said pressure exerting mechanisms to facilitate the matrix alignment operation.

112. In a slug casting machine equipped with a pair of line clamping jaws, at least one of

which is movable to and from normal full line receiving position before and after casting, respectively, the combination of a relatively fixed stop to locate the jaw in said position, and hydraulic mechanism for maintaining the jaw against the stop during casting.

113. In a slug casting machine equipped with a pair of line clamping jaws, at least one of which is movable to and from normal full line receiving position before and after casting, respectively, the combination of a relatively fixed stop to locate the jaw in said position, hydraulic mechanism for maintaining the jaw against the stop during casting, and automatic means operative before casting for relieving the hydraulic pressure exerted on the jaw to facilitate the matrix alignment operation.

114. In a slug casting machine, the combination of a pair of line clamping jaws, means for moving one or each of said jaws toward the other for quadding or centering, and mechanism for exerting an inward clamping pressure on the jaws while in quadding or centering position, said mechanism being conditioned to exert a greater clamping pressure on the jaws for centering than for quadding.

115. In a slug casting machine equipped with a pair of line clamping jaws, the left-hand jaw being movable inwardly and outwardly to and from normal full line receiving position before and after casting, respectively, the combination of a relatively fixed stop to limit the inward movement of the jaw and locate it in said full line receiving position, and mechanism for maintaining the jaw against the stop during casting.

116. A combination according to claim 115, wherein the relatively fixed stop is adjustable to different positions to accommodate lines of different length.

117. A combination according to claim 115, wherein the adjustable stop is provided with a jaw coupling element whereby the jaw will be adjusted simultaneously with the stop in either direction.

118. In a slug casting machine, the combination of a pair of line clamping jaws, at least one of which is movable from a full line receiving position to a quadding position and return, and an individual power unit for effecting such quadding movement of the jaw.

119. In a slug casting machine, the combination of a pair of line clamping jaws, at least one of which is movable from a full line receiving position to a quadding position and return, and an individual power unit operative during casting to hold the jaw under an inward clamping pressure in its quadding position.

120. In a slug casting machine, the combination of a pair of line clamping jaws, at least one of which is movable from a full line receiving position to a quadding position and return, an individual power unit for effecting such quadding movement of the jaw, an individual power unit operative during casting to hold the jaw under an inward clamping pressure in its quadding position, and timing means for controlling the automatic operation of the two said power units in proper sequence.

121. In a slug casting machine, the combination of a pair of line clamping jaws, at least one of which is movable from a full line receiving position to a quadding position and return, an individual power unit for effecting such quadding movement of the jaw, an individual power unit operative during casting to hold the jaw under

an inward clamping pressure in its quadding position, a spaceband driver to justify the line when the jaw is in its quadding position, an individual power unit for effecting the line justifying movement of the spaceband driver, and timing means for controlling the automatic operation of the three different power units in proper sequence.

122. A combination according to claim 121, wherein the spaceband driver is operated in two stages, and wherein the inward clamping pressure exerted on the quadding jaw is relieved between the said stages.

123. A combination according to claim 121, wherein the spaceband driver is operated in two stages, with a relatively light force in the first stage and with a relatively heavy force in the second stage, and wherein the inward clamping pressure exerted on the quadding jaw is relieved between the said stages.

124. A slug casting machine equipped with a pair of line clamping jaws, the right-hand jaw being mounted for movement into and out of operative relation to the left-hand jaw, as well as for movement toward and from the left-hand jaw when in operative relation thereto for quadding.

125. A slug casting machine equipped with a pair of line clamping jaws, the right-hand jaw being mounted for movement into and out of operative relation to the left-hand jaw, as well as for movement toward and from the left-hand jaw when in operative relation thereto for quadding, and with automatic means for effecting such movements of the right-hand jaw in proper sequence.

126. A slug casting machine equipped with a pair of line clamping jaws, the right-hand jaw being mounted for movement into and out of operative relation to the left-hand jaw, as well as for movement toward and from the left-hand jaw when in operative relation thereto for quadding, pneumatic means for effecting the movement of the right-hand jaw into and out of operative relation to the left-hand jaw, pneumatic means for effecting the quadding and return movements of the right-hand jaw, and automatically operated valve mechanism controlling

the operation of the two said pneumatic mechanisms in proper sequence.

127. In a slug casting machine, the combination of a pair of line clamping jaws, at least one of which is movable from a normal full line receiving position to a quadding position and return, power means for effecting such quadding movement of the jaw, hydraulic means for applying jaw clamping pressure, and line justifying mechanism with power devices for operating it, all of which are mounted in the vise frame as a complete assembly unit.

128. A combination according to claim 127, wherein the vise frame unit is pivotally mounted with reference to the main machine frame unit.

129. A combination according to claim 127, wherein the vise frame assembly unit is pivotally mounted with reference to the main machine frame unit, said vise frame unit also including a cam shaft for timing the various operative organs in the vise frame, and a driving connection between said cam shaft and the cam shaft forming part of the main machine frame unit, which connection is made and broken automatically as the vise frame unit is swung into and out of operative relation to the main frame unit.

130. In a slug casting machine, the combination of a pair of line clamping jaws, at least one of which is movable from a normal full line position into direct contact with the line and return for free or random quadding, and means operative independently of the jaw moving means and during casting to exert an inward line clamping pressure on the jaw while in quadding position and operative after casting to release said jaw for return movement.

131. In a slug casting machine, the combination of a pair of line clamping jaws movable simultaneously from a normal full line receiving position into direct contact with the line and return for centering, means operative independently of the jaw moving means and during casting to exert an inward clamping pressure on both jaws while in centering position and operative after casting to release said jaws for return movement, and means connecting the jaws to insure their equidistant movement.

JAMES C. PLASTARAS.
